UNITED STATES PATENT OFFICE.

WARD W. LINCOLN, OF ROCK FALLS, ILLINOIS, ASSIGNOR TO JOSEPH M. DENNING, OF CEDAR RAPIDS, IOWA.

WIRE-FENCE MACHINE.

No. 902,422.

Specification of Letters Patent.

Patented Oct. 27, 1908.

Application filed December 11, 1905. Serial No. 291,217.

To all whom it may concern:

Be it known that I, WARD W. LINCOLN, a citizen of the United States of America, and a resident of Rock Falls, in the county of Whiteside and State of Illinois, have invented certain new and useful Improvements in Wire-Fence Machines, of which the following is a specification.

This invention relates to that class of wire fence machines in which the respective ends of individual stay wire sections are twisted and coiled around adjacent strand wires, and the coils interlocked together, in the formation of the usual rectangular mesh wire fence. And the present improvement has for its object, in the main, to provide a simple and efficient structural formation and combination of parts by means of which the wire components of the fence have continuous travel through the mechanism during the operation of forming the fence.

Other and minor objects of the present improvement are to provide simple and effective mechanisms for feeding the stay forming wires to the cutting mechanisms; for cutting off the stay forming wire sections into different and predetermined lengths; for effecting a simultaneous operation of the twin series of twister or coiler heads, and for crimping the strand wires at the sides of the knots or coils of the stay wire sections thereon, and immediately after the fence fabric leaves the weaving heads, all as will herein-after more fully appear and be more particularly pointed out in the claims.

In the accompanying drawings illustrative of the present invention: Figure 1 is a side elevation, showing the main frame, etc., in dotted lines and the connecting gear wheels in full lines. Fig. 2 is a detail elevation of the commutators of the rotary carrier and rotary weaving heads of the machine. Fig. 3 is a general longitudinal section. Fig. 4 is a front elevation, with parts removed on line $x-x$, Fig. 3. Fig. 5, is a transverse sectional elevation on line $x'-x'$, Fig. 3. Fig. 6 is a detail plan of the rotary feed mechanism for the stay forming wires, and the straightening mechanism therefor. Fig. 7 is an axial detail sectional elevation of the rotary carrier and weaving heads, and their accessories. Fig. 8 is a detail sectional elevation of the feeding and cutting mechanisms for the stay forming wires. Fig. 9 is a detail horizontal section of the same on line x^2-x^2 , Fig. 8.

Fig. 10 is a detail horizontal section on line x^3-x^3 , Fig. 8, of a stationary knife block of the cutting mechanism. Fig. 11 is a detail transverse section of the rotary stay wire section carrier. Fig. 12 is a detail longitudinal section of the same. Fig. 13 is an end elevation of one of the electro-magnetic holders of the stay wire section carrier. Fig. 14 is a detail transverse section of the rotary weaving head of the machine. Fig. 15 is a detail plan view of the same. Fig. 16 is a detail longitudinal section of the same, on line x^4-x^4 , Fig. 15. Fig. 17 is a detail plan view of one end of the same. Fig. 18 is a detail elevation of one of the operating electro-magnets of the gripper jaws of the rotary weaving heads. Figs. 19, 20, 21, 22, 23, and 24 are detail plan views illustrating the various steps in the formation of the interlocking knots or coils of the stay wire section ends around the strand wires. Figs. 25, 26, 27, 28, and 29 are companion face views, additionally illustrative of the same. Fig. 30 is a diagram illustrating the movement of a coiler or twister pin in making the interlocking knot aforesaid. Fig. 31 is an unfolded view of the endless cam groove by which the cutting mechanisms for the stay wire sections are operated. Fig. 32 is a similar view of the endless cam groove by which a turning movement of the stay wire section holders is effected. Fig. 33 is a similar view of the endless cam groove by which the carrying rails of the twister heads are moved to and from each other. Fig. 33^a is a similar view of a modification of said cam. Fig. 34 is a similar view of the endless cam groove by which the rotation of the twister or coiler heads is effected. Fig. 34^a is a similar view of a modification of said cam. Fig. 35 is a detail plan view of a series of the twister heads illustrating a modified arrangement of parts for producing a simpler form of fence knot. Fig. 36 is a companion face view of the same. Fig. 37 is an elevation of a section of fence formed by the modified mechanism shown in Figs. 35 and 36.

Similar numerals of reference indicate like parts in the different views.

Referring to the drawings:—1 represents a pair of side plates suitably connected together to constitute the stationary supporting frame in which the different operative mechanisms of the machine are supported.

2 are a series of wire straightening mechan-

105
110

isms of any ordinary construction, mounted on the main frame 1, and through which the series of strand wires which enter into the making of the fence fabric are drawn and straightened in their passage to the rotary weaving head of the machine. 3 are a similar series of wire straightening mechanisms also mounted on the main frame 1, and through which a series of wires adapted to 5 form the stay wire sections of the fence fabric are drawn and straightened in their passage to the feeding and cutting mechanisms.

4 are a series of intermittent feed mechanisms, hereinafter described in detail, by 10 which the series of wires, from which stay wire sections are to be formed, are intermittently fed to the series of cutting mechanisms.

5 are the series of cutting mechanisms, 15 hereinafter described in detail, by which the last mentioned wires are severed into proper lengths to constitute the stay wire sections of the fence fabric.

6 is a rotary carrier head journaled in the 20 main frame 1, in parallel and adjacent relation to the aforesaid series of cutting mechanisms 5 and intermediate of the same and the rotary weaving head of the machine. Such carrier head is provided with longitudinal 25 rows of automatic gripping or holding jaws, hereinafter described in detail, which individually grip or engage the series of stay wire sections as they are severed by the aforesaid series of cutting mechanisms, and transport and deliver the same to corresponding 30 longitudinal rows of gripping jaws carried by the rotary weaving head of the machine.

7 is the rotary weaving head of the 35 machine, journaled in the main frame 1, and provided with longitudinal rows of gripping jaws and longitudinal rows of rotary coiler or twister heads, hereinafter described in detail, and which are adapted to engage and twist or coil the ends of the stay wire sections around the series of strand wires in the 40 operation of making a rectangular or square-mesh wire fence.

8 is the strand wire crimping mechanism, hereinafter described in detail, and through 45 which the fence fabric passes as it leaves the rotary weaving head, and by means of which the strand wires are crimped at each side of the convolutions of the stay wire sections upon said strand wires, with a view to prevent 50 creeping of the stay wire sections upon the strand wires in the subsequent handling and use of the fence fabric.

9 are a series of "pull out" wheels of any 55 usual construction adapted for positive engagement with the fence fabric. Such wheels are mounted on a common carrying shaft 10, journaled in the main frame, and are adapted to engage the fence fabric as it leaves the wire crimping mechanism 8, and afford 60 assistance in pulling the fence fabric

through said mechanism, as well as the strand wires through the straightening mechanism 2, and around the weaving head 7, before referred to. In the construction shown the fence fabric is arranged to lap 70 around the greater part of the peripheries of said pull out wheels 9 with a view to afford a substantial and equalizing pulling out stress upon the fence fabric.

11 is an idler drum under which the fence 75 fabric passes on its way to the reeling mechanism.

12 is the reeling mechanism, of any usual and suitable construction, arranged at the delivery end of the machine, and adapted to 80 reel up the fence fabric as it comes from the weaving and crimping mechanisms before referred to.

The series of intermittent stay wire feeding mechanisms 4, before referred to, comprise in detail a structural formation and arrangement of parts as follows:—13 are a series of feeding wheels carried by a common carrying shaft 14 intergeared with the shaft 85 of the rotary carrier head 6 by gear wheels 15 and 16, so as to have constant rotation in unison therewith. Such feeding wheels are located at graduated distances apart corresponding to a like arrangement of the coiler or twister heads of the rotary weaving heads 90 7, and each of said feeding wheels is provided with a continuous flange 17 at one end and with a series of flange plates 18 at the other end to provide a peripheral channel for the reception of a bend or bight in the stay 95 forming wire which is to be fed. Such bend or bight in the wire may consist of a quarter bend, or one or more circular loops or coils in said wire, in accordance with the size and resiliency of the wire employed.

19 are a series of tension disks or rolls carried by a common carrying shaft 20 intergeared with the shaft 14 of the feeding wheels 13 by gear wheels 21 and 22, so as to have constant rotation in unison therewith. Such tension 100 disks are located on the shaft 20, in a like graduated manner to that of the feeding wheels 13 with their peripheries in adjacent 105 relation to the peripheral channels aforesaid of the feeding wheels 13, to produce a binding 110 action of the opposed portions of such peripheries upon the portions of the stay forming wires in position therebetween, and set up a frictional adhesion of the said wires upon the peripheries of the feeding wheels 115 120 between the continuous flange 17 and flanged plates 18 and a positive feed of the wires due to the extended frictional adhesion thus set up between said wires and the peripheries of said feeding wheels. In such 125 feeding mechanism, the series of straightening rolls 3, or other equivalent means for retarding the travel of the stay-forming wires, are necessary and coacting elements in effecting the practical operation of the feeding 130

mechanisms; and the operation of the present mechanism is identical with an ordinary capstan for pulling heavy loads, a wire feeding wheel 13 of the present mechanism representing the capstan drum; the wire straightening mechanism 3 representing the load to be moved by the capstan, and the tension disk or roll 19 representing the operator pulling on the free end of the capstan rope to govern the amount of frictional adhesion of the capstan rope around the periphery of the capstan drum. In order to render such wire feeding operations intermittent in their action, more or less of the peripheries of the respective tension disks 19 will be cut away, as illustrated in Fig. 8, so as to afford a greater or less duration of the binding and feeding action just described, and so that each individual feeding mechanism of the series may feed to its individual cutting mechanism sufficient wire to have an individual stay wire section of a required and predetermined length. 23 is a stationary rail arranged in the main frame 1, and having a vertical face arranged tangentially to the peripheries of the aforesaid series of feeding wheels 13 to constitute a vertical breast or abutment for the ends of the stay forming wires, as herein-after set forth. 24 are a series of holding levers, corresponding in number and arrangement with the series of feeding wheels and tension disks just described. Each of said holding levers is individual to a feeding wheel and tension disk, and is adapted for engagement, in manner hereinafter described, with the individual stay forming wire engaged by such feeding wheel and tension disk. 25 is a yielding or resilient toe carried by the lower arm of each lever 24 and adapted in the operation of the mechanism to press the free end of a stay forming wire against the breast rail 23, and hold the same in proper position during the inactive condition of an individual feeding mechanism. 26 is a cam groove formed in the side of each tension disk 19, aforesaid, and adapted for operative engagement with the upper arm of a holding lever 24, and such cam groove is so positioned as to cause the resilient toe 25 of the lever to engage a stay forming wire during an inactive condition of the individual feeding mechanism and prevent a further downward movement of the stay forming wire to the cutting mechanism. 27 are a series of hard abutment plugs inserted in the breast rail 23, to resist wear and abrasion due to the passage of the stay forming wires aforesaid.

The series of intermittent stay wire cutting mechanisms 5, before referred to, comprise in detail a structural formation and arrangement of parts as follows: 28 are a series of stationary vertical posts supported between the underside of the breast rail 23, and a lower rail 29 of the main frame, and corre-

sponding in number and arrangement with the series of feeding mechanisms above described. 30 are a series of stationary shear blocks secured in a vertically adjustable manner on the vertical posts 28, by clamping screws, as shown in Figs. 8 and 10. Each of said shear blocks is provided with a vertically apertured guide bushing 31, and with a cutter blade 32 at its lower end. 33 are a series of vibratory shear heads journaled on the vertical posts 28 beneath the stationary shear blocks 30, and adapted in their vibratory movements to shear off from the stay forming wire sections of the proper length. 34 are a series of sleeves surrounding the vertical posts 28 and inserted between the shear heads 33 and the lower rail 29 aforesaid to support said shear heads in proper vertical position. In practice such sleeves 34 will have different vertical heights, so that the vertical locations of the aforesaid shear heads and blocks can be raised or lowered to compensate for the different lengths in a series of stay wire sections which are severed at a single period in the operation of the machine; for the longest stay wire section, the sleeve 34 of the individual cutting mechanism therefor will be of sufficient height to support such cutting mechanism in a position immediately beneath the breast rail 23, as illustrated in Fig. 8; while for the shortest stay wire section no sleeve 34 need be used, but instead the individual cutting mechanism therefor may rest directly upon the transverse lower rail 29 above described. 35 is a transverse shaft, see Fig. 5, journaled on the main frame 1, and which may be one of the pair of carrying shafts 35, 36 of the rotary crimping mechanism hereinafter described. 37 is a cam wheel mounted on the shaft 35 and provided with a peripheral cam groove of the form shown in an unfolded condition, Fig. 31. 38 is a cam lever pivoted to the main frame, with one arm in operative engagement with the cam groove of the cam wheel 37, and with its other arm operatively connected to the transverse bar or shaft now to be described. 39 is a bar or shaft having transverse reciprocation in bearings in the main frame 1, and operatively engaged by the cam lever 38, aforesaid. 40 are a series of blocks carried by the bar or shaft 39 and individual to the series of stay cutting mechanisms heretofore described. Each of said blocks is formed with an elongated vertical channel 41, as illustrated in Fig. 8, and in which the rear end of the arm 42 of an individual vibratory shear head 33, has operative engagement, in a manner to permit of the before described vertical adjustment of said shear head without disturbing the operative engagement of the parts.

The rotary carrier head 6, before referred to, and by means of which the series of stay wire sections, as severed by the series of cut-

ting mechanisms, are engaged, carried around and delivered to the rotary weaving head, comprises in detail a structural formation and arrangement of parts as follows:—43 is 5 a transversely arranged supporting shaft, journaled in the main frame 1, and intergeared with the carry-shaft of the rotary weaving head 7 by gear wheels 44 and 45, so as to have constant rotation in unison therewith. 46 are a series of rails supported in parallel and concentric relation to the axis of the shaft 43 by end supporting heads or disks 47, secured to the shaft 43. Each of 10 said rails is formed with a series of radial journal orifices corresponding in number and arrangement with the series of cutting mechanisms heretofore described, and adapted to afford bearings for the radially arranged hubs of an individual row of stay wire section 15 grippers or holders, now to be described. 48 are the series of rows of stay wire section gripper or holder heads above referred to; each of which is formed with a cylindrical hub portion having bearing in an individual bearing orifice of a rail 46 aforesaid, and confined in place by confining collars 49 and 50 20 on its respective ends, as illustrated in Figs. 11 and 12. 51 is a segmental gear formed in the periphery of the hub just referred to, and adapted for operative engagement with a transversely extending gear bar or rack 52, common to a single transverse row of the holder or gripper heads and adapted to impart simultaneous partial rotation to such 25 row of heads. 53 is a stationary cam ring secured to the main frame 1, so as to surround the carrying shaft 43 of the above mechanism; and such cam ring is provided with an endless cam groove, of the form shown in an 30 unfolded condition in Fig. 32, and in which rollers on the ends of the respective rack bars 52 have engagement to afford operative connection between said parts. The arrangement is such that an orbital travel of such 35 rack bars around the cam ring 53 will cause a reciprocation of such rack bars at proper intervals, as hereinafter more fully stated in the operation of the machine, to impart a desired partial rotary movement to the gripper 40 or holder heads 46, to the extent of a quarter turn, and a subsequent return to the starting or normal position. 54 are radially projecting jaws arranged at the outer end of each hub portion of a gripper or holder head 48, 45 and provided with V-shaped channels or recesses in their outer ends to receive and hold the stay wire section, and to such end the circular path traversed by said jaws is made to intersect or closely approach the path of 50 the stay wires as they depend from the cutting mechanisms aforesaid. In the present improvement each of the jaws 54 constitutes one pole piece of an electro-magnet 55 so that when said electro-magnet is electrically energized the said jaws will engage and hold the 55

stay wire sections during the period of such energization. Said electro-magnets will be of any usual construction, and will be attached on the outer ends of the aforesaid hub portions of the holder heads 48, in an adjustable 70 manner by set screws 56 passing through curved slots 57 in the base portion of said electro-magnets, and screwing into the outer ends of said hub portions, as illustrated in Figs. 11 and 13. 58 is a cylindrical commutator as shown in Figs. 2, 4 and 7 carried by the shaft 43, with its respective commutator bars individually connected to the respective rows of electro-magnets 55, in any usual and approved manner. 59 is a multiple commutator brush or contact member, carried on the main frame 1, and connected in any usual manner with a source of electro-motive force. In the type of fence machine shown in the present drawings, such commutator 80 brush 59 is adapted to contact with three of the eight commutator bars of the commutator 58, so that the electro-magnets 55, within the range between the stay wire cutting mechanisms and the point at which the stay 85 wire sections are delivered to the rotary weaving head, will be electrically energized to firmly hold the stay wire sections in the holding jaws 54, as will more fully appear in the description of the operation of the machine. 90

The rotary weaving head 7, before referred to, and by means of which the ends of the stay wire sections are coiled or twisted around the strand wires of the fence fabric, 100 comprises in detail a formation and arrangement of parts as follows:—60 is a transversely arranged shaft journaled in the main frame 1, and intergeared with the shaft 43 of the carrier head by gears 44 and 45, before 105 described, and also intergeared with the carrying shafts of the crimping mechanism 8, as hereinafter described. 61 are end supporting disks or rings secured in separated relation on the shaft 60, and connected together by a 110 series of bars or staves 62, of an angular form in cross section, to constitute a skeleton supporting frame for the operative parts of the weaving mechanism, as shown in Figs. 3, 4, 7, 14 and 17 of the drawings. 63 are a series 115 of pairs of rails in which the multiple rows of coiler or twister heads of the present invention are mounted. Each pair of said rails is connected at their respective ends to the peripheries of the end disks 61 aforesaid, in a 120 manner which admits of limited and simultaneous reciprocation of each pair of said rails to and from each other, by means as follows:—64 are toothed racks on the respective ends of each pair of rails 63, aforesaid, and 125 having an opposed and parallel relation to each other, as shown in Figs. 4, 7 and 17. 65 are a series of toothed pinions journaled between the pairs of racks 64, and having operative engagement therewith, so that a par. 130

tial rotation of the pinions in one direction or the other will impart simultaneous movements in opposite directions to the racks, and to the rails 63, by which they are carried.

5 66 are a series of cam arms, individual to the aforesaid pinions 65 and provided at their free ends with cam rollers or like means for operative engagement in the cam grooves of the cams by which automatic movements of 10 the cam arms and pinions aforesaid are effected. 67 are a pair of stationary cam rings arranged in concentric relation to the axis of the shaft 60, and provided with counterpart endless cam grooves on their inner 15 surfaces of the form shown in an unfolded condition in Fig. 33, for engagement with the cam arms 66, aforesaid. The arrangement is such that an orbital travel of the rails 63, and the above described accessories, in relation to the stationary cam rings 67, will cause a reciprocation of said rails to and from each other, as pairs, at the proper intervals, as more fully set forth in the operation of the machine, to advance and retract the twister 20 heads in the operation of coiling the ends of the stay wire sections upon the strand wires of the fence fabric. 68 are segmental shoes upon the main frame, in which the lower portions of the peripheries of the cam rings 67 25 rest and are supported in a manner to permit of a turning adjustment of said cam rings in effecting the proper timing of the mechanism. See Figs. 3, 4 and 7. 69 are the coiler or twister heads of the machine, journaled in 30 rows in the series of rails 63, aforesaid, as illustrated in Figs. 4, 7, 14, 15, and 16, with the series of coiler or twister heads in each 35 row corresponding in number and transverse arrangement with the before-described stay wire feeding, cutting and carrying mechanisms. Each coiler or twister head 69 is formed 40 with the usual axial and open side runway 70 for the reception and passage of an individual strand wire; with a central pinion portion 71, for operative engagement with the rack-bar hereinafter described; with end bearing necks 72 affording bearings for the twister head in the rail 63, and with one or 45 more coiler or twister pins 73, as hereinafter more particularly set forth in the description 50 of the operations of coiling or twisting the stay wires upon the strand wires in the formation of different varieties of the fence. 74 are a series of rack-bars extending the length 55 of the series of rails 63, and each rack bar has operative engagement with the pinion portions 71 of one row of twister heads 69, and is adapted to impart simultaneous rotation to such row of twister heads. 75 are stationary cam rings secured to the main frame 1 in 60 concentric relation to the shaft 60 of the above mechanism, and provided with counterpart endless cam grooves on their inner surfaces, of the form shown in an unfolded condition in Fig. 34, for operative engagement

with cam rollers 76 secured to the ends of the rack bars 74, as illustrated in Figs. 4 and 7; and the arrangement is such that an orbital travel of the rack bars 74, with relation to said cam rings 75, will cause a simultaneous 70 turning movement of the rows of twister heads 69, in one direction or the other, and at proper intervals, as hereinafter more fully set forth in that part of the operation of the machine involving the movements of the 75 twister heads.

The preferred form of the present mechanism, illustrated in Figs. 1 to 34 inclusive, is intended to produce the form of knot of the stay section wire ends upon the strand wires 80 shown in course of formation in Figs. 19 to 29 inclusive, and to such end each pair of rows of twister heads 69 will have an opposed relation in each pair of opposing rails 63, before described, and each twister head will be provided with a single twister or coiler pin 73, as illustrated more particularly in Fig. 15.

In Figs. 35 and 36 is shown a modified arrangement of the twister or coiler heads, and in which use is made of single rows of twister 90 heads provided with duplicate twister or coiler pins 73', instead of the before-described pairs of opposed rows of twister heads provided with single twister pins 73, the single rows of twister heads operating to weave the 95 ordinary form of wire fence shown in Fig. 37, in a manner hereinafter set forth in the operation of the machine.

77 are a series of fixed standards secured in rows to the before described bars or staves 100 62, at points midway between the twister heads 69 of each row of the same, as illustrated more particularly in Figs. 7 and 16.

78 are a series of pairs of gripper levers pivoted to the series of standards 77 with 105 their upper arms forming gripper jaws between which the stay wire sections are received and gripped in the operation of the mechanism.

79 are a series of springs arranged between 110 the lower arms of the series of pairs of gripping levers 78 with a normal tendency to force the gripping jaws aforesaid together, in a manner to permit the stay wire sections being forced between them by the stay wire 115 carrier jaws 54 before described, as individual rows of said gripper jaws and carrier jaws move towards a common and intersecting path in the actual operation of the machine.

80 is an armature carried by the lower end 120 of each gripper lever 78 aforesaid.

81 is an electro-magnet secured to a bar or stave 62, aforesaid, and adapted when energized to exert a powerful pulling action upon its gripper lever 78 and effect a forcible holding 125 of the stay wire section by the gripper jaws of a pair of said levers during the period in which their electro-magnets are so energized.

82 is a cylindrical commutator carried by the shaft 60 with its respective commutator 130

bars individually connected to the electro-magnets 81 of each row of gripper levers 78 in any usual and approved manner.

83 is a multiple commutator brush or contact member as shown in Figs. 2 and 7 carried on a stationary part of the machine, and connected in any usual manner with a source of electro-motive force. In the construction shown in Fig. 2 of the drawings, such commutator brush 83 is adapted to contact with three of the eight commutator bars of the commutator 82, but such range of contact may be increased or diminished as the judgment of the constructor or the nature of the wire used to form the stay wire sections may indicate; the requirement being that the stay wire sections must be positively held against endwise slip until sufficient initial twisting of the stay wire ends around the strand wires has been effected to prevent any tendency to an endwise slip of the stay wire sections when the gripping jaws 78, are released.

The crimping mechanism 8, before referred to, comprises in detail a formation and arrangement of parts as follows: 35 and 36 are a pair of transversely arranged shafts, heretofore referred to, journaled in the main frame 1, and intergeared together by gears 84 and 85, and by idler gear 86, with the gear 45 of the carrying shaft 60, of the weaving head 7 of the machine. 87 are a series of disks or collars secured in separate relation on the respective shafts 35 and 36, and connected together by a series of rails or staves 35 88, to constitute a series of separated skeleton supporting frames upon each of said shafts, for the series of crimping dies, now to be described. 89 are the series of crimping dies secured to the outer faces of the rails 88, 40 with their respective die faces in concentric relation to the axis of the respective shafts 35 and 36, and so that in their orbital travel around their shafts, the opposed die faces will intermesh, as illustrated in Fig. 3, to 45 impart a crimp to the strand wire at the respective sides of the knob or twist of the stay wire upon said strand wire. To such end each die will be provided with a central depressed portion, to receive the knob or 50 twist just referred to, and with prongs or teeth, at each side of said central depressed portion, to form the last referred to crimps in the strand wires; such being an ordinary construction in the present class of wire fence 55 machines.

With the above described type of rotary crimping mechanisms, much difficulty has been met, owing to the springing apart of the carrying shafts 35 and 36 under the stress required in forming the crimps, and a consequent imperfect formation of the same. With a view to remedy such defect, one part of the present improvement involves a structural formation and arrangement of parts as follows:—90 are bearing shoes located be-

tween the two supporting frames aforesaid and adapted to have bearing upon the carrying shafts 35 and 36, as shown in Fig. 5. 91 are girders arranged in parallel relation to the shafts 35 and 36, and in a plane beyond 7 the orbit of the crimping dies 89, and adapted to carry the bearing shoe 90, above described. 92 are tie bolts connecting said girders together, and arranged at the respective ends of said girders and out of the path of the fence 75 fabric passing through the crimping mechanism. By such construction the shafts 35 and 36 are rigidly braced together against any tendency to spread apart under a heavy strain, and without any interference with the 80 passage of the fence fabric through the crimping mechanism. 93 and 94 are gears connecting the carrying shaft 10 of the series of pull out wheels 9 with the gear 85 of the crimping mechanism so as to have constant rotation in unison therewith. 85

The operation of the machine is as follows: The series of strand wires from suitable reels or other supply source are drawn through the series of straightening rolls 2, and thence 90 to the rotary weaving head 7, where such strand wires are received in the open side axially extending runways 70 of the series of twister heads 69 peripherally mounted on said weaving head 7. At the same time the 95 series of stay forming wires are drawn through the series of straightening rolls 3, and from thence pass to and around the series of feeding wheels 13 of the intermittent wire feed mechanism 4 and between said 100 feeding wheels 13 and the tension disks 19, as set forth in the prior description of such mechanism, to be fed in an automatic manner to the intermittent cutting mechanisms 5, by means of which stay wire sections are 105 severed from such stay forming wires. Simultaneous with the cutting of a series of stay wire sections, as aforesaid, a row of the gripper or carrier jaws 54 of the rotary carrier head 6, moves into a position midway 110 the length of the section of stay wires being severed, and at the same time becomes electrically energized, through the instrumentality of the commutator cylinder and brush 58 and 59, to magnetically engage and hold 115 the stay wire sections. With the continued rotation of the carrier head 5, and during a quarter turn of the same, the row of gripper or carrier jaws 54 are given a quarter turn upon their individual axes by means of the 120 segmental gears 51, rack bar 52, and cam ring 53, as heretofore described in the description of the carrier head, and so that before such row of gripper or carrier jaws 54, reach their point of intersection or delivery 125 with or to the gripper or holding jaws 78 of the rotary weaving head 7 they will have turned the series of stay wire sections in a direction transverse to the series of strand wires on the weaving head. As the said 130

series of carrier jaws 54 have a circular path which intersects a like circular path of the gripper jaws 78 of the weaving head, their action will be to force the series of stay wire sections into the said gripper jaws as the two series of jaws move into such intersecting path. The forcing of the stay wire sections into the jaws 78 is effected against the stress of the springs 79, and with such introduction of the stay wire sections, the energizing electric current is cut off from the electro-magnets 55 of the row of jaws 54 by the commutator 58 while, coincident therewith, the commutator 82 completes the circuit of the electro-magnets 81 of the row of gripper jaws 78 to effect a substantial grip of such jaws 78 upon the sections of the stay wire held therein. The holding faces of the jaws 78 are arranged slightly inclined to the axis of the weaving head 7 so that adjacent ends of the stay wire sections may project past each other without interference, as illustrated more particularly in Fig. 15; and in order that the stay wire sections may have the required length to form the respective twists or knots upon the lowermost fence strands which, in the present class of fences, are arranged as close together as three inches, the jaws 78 next to the delivery end of the machine will be partly cut away to afford room for such stay wire ends, as clearly shown in Figs. 15 and 16. With the stay wire sections firmly held in the jaws 78, due to a continued energization of their electro-magnets 81, and with the respective ends of the stay wire sections extending across the strand wires, the coiling or twister pins 73, of twister heads 69, engage the ends of the stay wire sections to wrap the same around the strand wires. Such description applies to the usual wrapping of the stay wire sections upon the upper and lower strand wires of the fence fabric where only individual twister heads will be required to effect the operation, and needs no special description other than that which will appear in the following description of the formation of the knots upon the intermediate strand wires.

For the stay wire sections engaging the intermediate strand wires of the fence fabric, and in the formation of a particular interlocked knot or twist, the preferred form of the machine as heretofore described will be employed, and a pair of opposed twister heads 69, each having a single twister or coiler pin 73, will be used to form each knot by a cycle of operations as follows: Under the influence of the cams 67, the pair of carrying rails 63 are moved towards each other from the initial position shown in Fig. 19, to effect a corresponding initial movement of the pair of twister heads 69 together, and so that their individual coiling pins 73 will overlie the respective ends of the two stay wire sections which are to be knotted or twisted around a particular strand wire, as shown in Fig. 20. With the coiling pins 73, overlying the stay wire ends as above set forth, the cams 75 are adapted to impart movement to a pair of the rack bars 74, which in turn imparts to each 70 twister head 69, and their coiling pins 73, a partial rotation approximately 73° as illustrated in diagram view, Fig. 30. Such coiling pins in turn impart a partial downward bend to the respective stay wire ends, as 75 shown in Figs. 21 and 26; coincident therewith the twister heads and carrying rails continue to advance towards each other, so that while the above mentioned bends are being formed in the ends of the stay wire sections, the said bent ends are forced in opposite directions and cross or intersect each other as shown in Figs. 21, 22 and 23. The twister heads 69 then receive a partial reverse rotation approximating 8° , as indicated 80 in diagram view, Fig. 30, under the influence of the cams 75, and in order to free the coiling pins from the bends just formed in the stay wire ends; after which the carrying rails 63, and twister heads 69, under the influence 85 of the cams 67, move apart a sufficient distance to remove the coiler pins 73 into paths which do not intersect the just formed bends in the stay wire sections. When moved apart sufficiently the twister heads, under 90 the influence of the cams 75, make partial forward rotations approximating 134° , as indicated in diagram view, Fig. 30. The carrying rails 63 and twister heads 69, under the influence of the cams 67, are then moved to 95 towards each other, so that each respective coiling pin will engage the respective stay wire end which had been bent as before described by the other coiling pin. The direction of rotation of the twister heads again 100 reverses and under the influence of the cam 75 said twister heads make one and one half forward revolutions, approximately, to effect a corresponding coiling of the stay wire ends upon the strand wire, and complete the 105 interlocked knot. During such coiling or twisting of the stay wire ends upon the strand wire, the carrying rails and twister heads move apart under the influence of the cams 67, and in accordance with the gradual 110 formation of the knot. With such completion of the knot, the twister heads, under the influence of the cams 75, make a reverse rotation, approximating one full turn, in order 115 to be in their initial position first described, ready for a fresh cycle of operations required in the formation of a succeeding knot.

In the knot forming method just described, the formation of the knots takes place during the orbital travel of the twister heads around 120 the axis of the rotary weaving heads 7, upon which said twister heads are mounted; this permits of the travel of the strand wires through the machine in a continuous manner, so that two or more transverse series of 125 130

fence knots may be in course of formation at one and the same time. The resulting advantages therefrom are that ample time can be afforded to form the knots; a corresponding decrease in the strain on the mechanism, and an increase in the amount of fence fabric produced in a given time.

At any period after the stay wire sections are sufficiently coiled around the strand wires to hold, the circuit may be broken on the electro-magnets 81 of the particular row of gripper jaws 78 in order that the finished portion of the fence fabric will be free to be drawn away from engagement with said gripper jaws in a continued operation of the machine.

The finished fence fabric leaving the weaving head 7, as above stated, passes through the crimping mechanism 8, which crimps the strand wires at each side of the knots, and from thence to the pull out wheels 9 and under the idler drum 11 to the reeling mechanism 12, as usual in wire forming machines of the present class.

In the operation of the modified form of the mechanism shown in Figs. 35 and 36, for the production of a wire fence of the construction shown in Fig. 37, the arrangement and operation of the different mechanisms will be substantially the same as above set forth, the exceptions being as follows:—

The substitution for the rotary, carrier head 6, heretofore described, of the particular type of ordinary wire feeding mechanisms in which the stay wire sections are fed in a lateral and inclined direction, so as to place one adjacent stay wire end above, and the other adjacent stay wire end beneath a strand wire. The substitution for the companion rows of twister heads heretofore described, of individual rows of twister heads, with each twister head provided with duplicate coiling pins 73', as shown in Figs. 35 and 36. A modification of the cams 67 from the form shown in Fig. 33 to that shown in Fig. 33^a to effect a "backing off" of the twister heads as the coiling of the fence knots progresses, instead of the more complex movements of the twister heads, heretofore described. And a modification of the cams 75 from the form shown in Fig. 34 to that shown in Fig. 34^a, to effect a turning movement of the coiler heads, in the operation of the modified mechanism just described.

Having thus fully described my said invention, what I claim as new and desire to secure by Letters Patent, is:—

1. In a wire fence machine, a revoluble frame, twister heads mounted on the surface of the frame in pairs of opposite rows and extending around the frame and also longitudinally of the frame, each twister head having an acting end face adapted to engage the ends of the sections of a transverse stay

wires, and a rack-bar in mesh with the twister heads of each longitudinal row of twister heads, the rack-bars of two companion rows having reciprocating movements in opposite directions at the same time to actuate in succession two rows of companion twister heads in opposite directions and coil the ends of the stay wire sections around the strand wires, substantially as described. 70

2. In a wire fence machine, a revoluble frame, twister heads mounted on the surface of the frame in pairs of opposite rows and extending around the frame and also longitudinally of the frame, each twister head having an acting end face adapted to engage the 75 ends of the sections of a transverse stay wire and coil said ends around the strand wires, a rack-bar in mesh with the twister heads of each longitudinal row of twister heads, the rack-bars of two companion rows having reciprocating movements in opposite directions at the same time to actuate in succession two rows of companion twister heads in 80 opposite directions and coil the ends of the stay wire sections around the strand wires, a 85 rack-bar in mesh with the twister heads of each longitudinal row of twister heads, the rack-bars of two companion rows having reciprocating movements in opposite directions at the same time to actuate in succession two rows of companion twister heads in 90 opposite directions and coil the ends of the stay wire sections around the strand wires, and means for inaugurating the opposite movement of the successive pairs of rack-bars at the same point in their travel to facilitate the actuation of said twister heads, 95 substantially as described.

3. In a wire fence machine, a revoluble frame, a series of slotted twister head brackets supported on said frame, two companion rack-bars longitudinally movable through each row of brackets, two opposite slotted 100 twister heads revolvably mounted in each bracket and each in mesh with its operative rack-bar, each twister head having an acting end face adapted to engage the ends of the sections of a transverse stay wire and coil 105 said ends around the strand wires, and means operating at a given point in the rotation of the frame for reciprocating the two companion rack-bars in opposite directions at the same time and thereby rotate the two companion twister heads in opposite directions for each twister head to coil the overlapping end of a transverse stay wire section around the strand wire, substantially as described. 110

4. In a wire fence machine, a revoluble 115 frame comprising a revoluble shaft, supports fixedly mounted on said shaft to rotate therewith, a series of twister heads arranged in opposite pairs and mounted in circumferential rows on said supports, each twister 120 head having an acting end face adapted to engage the ends of the sections of a transverse stay wire and coil said ends around the strand wires, a series of longitudinally movable rack-bars on said supports, two companion rack-bars in mesh with two companion series of twister heads, the two companion rack-bars having reciprocating movements in opposite directions to revolve the 125 companion series of twister heads in oppo- 130

site directions for coiling the ends of the transverse stay wire sections around the strand wires, and means for inaugurating the opposite movement of each pair of succeeding rack-bars at the same point in their travel, substantially as described.

5. In a machine of the class described, a revoluble frame, twisting devices journaled in said frame and disposed in opposite companion longitudinal rows, each twisting device having an acting end face adapted to engage the ends of the sections of a transverse stay wire and coil said ends around the strand wires, and rack bars reciprocally supported and arranged in pairs on said frame, each companion pair of rack bars adapted to actuate the twisting devices of companion series and operate companion twisting heads in opposite directions to coil the ends of the 20 sections of the transverse stay wire around the strand wires, substantially as described.

6. In a wire fence machine, parallel frame supports mounted on a revoluble frame, a series of rotating twister heads journaled in the 25 frame supports and arranged opposite each other and at graduated distances from each other, each twister head having an acting end face adapted to engage the ends of the sections of a transverse stay wire and coil 30 said ends around the strand wires, means engaging said twister heads and actuated by power devices carried at one end of the frame support and operating to rotate companion twister heads in opposite directions for coiling the ends of the transverse stay wire sections 35 around the strand wires, and means for actuating said power devices of companion twister heads in opposite directions, substantially as described.

40 7. A wire fence machine, comprising a rotating frame, a series of opposite companion rows of twisting devices arranged in said frame, each companion row of twisting devices consisting of a plurality of twister 45 heads and each twister head having an acting end face adapted to engage the ends of the sections of a transverse stay wire and coil said ends around the strand wires, power devices engaging each companion independent 50 row of twister heads and operating to revolve the twister heads of companion rows in opposite directions to coil the ends of the transverse stay wire sections around the strand wires, and means engaged by said power devices for intermittently actuating each successive row of twister heads, as and for the purpose described.

8. In a machine for making wire fabric, the combination with a drum, of a plurality 60 of twister supports removable from the drum and companion sets of twister heads carried by each support and removable therewith, the twister heads of each set each having an acting end face adapted to engage the ends of

the sections of a transverse stay wire and coil 65 said ends around the strand wires, substantially as described.

9. In a machine for making wire fabric, the combination with a drum, a plurality of 70 twister supports removable from the drum, two companion sets of twister heads carried by each support and removable therewith, each twister head of the companion series having an acting end face adapted to engage the ends of the sections of a transverse stay 75 wire and coil said ends around the strand wires, and means movable longitudinally through the supports and beneath the two companion sets of twister heads and operating in the longitudinal movement to revolve 80 the twister heads of the two sets in opposite directions adapted at intervals to actuate such twister heads and coil the ends of the sections of the transverse stay wire around the strand wire, substantially as described. 85

10. In a machine for making wire fabric, the combination with a drum, of a plurality of twister supports removable from the drum, and two sets of companion twister 90 heads carried by each support and removable therewith, each twister head of the companion sets of twister heads having an acting end face adapted to engage the ends of the sections of a transverse stay wire and coil 95 said ends around the strand wires, substantially as described.

11. In a wire fence machine, a fence forming drum, means for holding the running wires of the fence fabric circumferentially on said drum, and twister heads mounted in 100 companion rows on said drum, each row comprising a plurality of twister heads, each twister head having an acting end face adapted to engage the ends of the sections of a transverse stay wire and coil said ends around 105 the strand wires, and the companion rows of twister heads revoluble in opposite directions for uniting the running wires with a transverse sectional stay wire extending longitudinally of the drum by coiling the ends of the 110 transverse stay wire sections around the running wires, substantially as described.

12. In a wire fence machine, a fence forming drum having at intervals opposite longitudinally movable rack-bars arranged in 115 pairs, the bars of each pair having longitudinal movements in opposite directions, slotted twisters, each twister having a driving wheel and oppositely arranged in pairs and mounted with the driving wheels of each pair of 120 twisters in mesh with a pair of rack-bars, each twister having an acting end face adapted to engage the ends of the sections of a transverse stay wire and coil said ends around the strand wires, and a single means for both 125 revolving the drum and actuating each pair of rack bars in opposite directions for oppositely revolving each companion pair of

twister wheels to coil the ends of the sections of the transverse stay wire around the strand wires, substantially as described.

13. In a wire fence machine, a fence forming drum having at intervals opposite longitudinally movable rack-bars arranged in pairs, the bars of each pair having longitudinal movements in opposite directions, slotted twistlers, each twister having a driving wheel and oppositely arranged in pairs and mounted with the driving wheels of each pair of twistlers in mesh with a pair of rack-bars, each twister having an acting end face adapted to engage the ends of the sections of a transverse stay wire and coil said ends around the strand wires, and a single means for actuating each pair of rack-bars in opposite directions of movement and returning the same successively as the drum is revolved, for the opposite movements of the two rack-bars to oppositely revolve the pairs of twistlers to coil the ends of the sections of a transverse stay wire around the strand wires, substantially as described.

14. In a wire fence machine, a fence forming drum having at intervals opposite longitudinally movable rack-bars arranged in pairs, the bars of each pair having longitudinal movements in opposite directions, slotted twistlers, each twister having a driving wheel and oppositely arranged in pairs and mounted with the driving wheels of each pair of twistlers in mesh with a pair of rack-bars, each twister having an acting end face adapted to engage the ends of the sections of a transverse stay wire and coil said ends around the strand wires, means for actuating the rack-bars of a pair successively and in opposite directions as the drum is revolved for the opposite movement of the two companion rack-bars to revolve the pair of companion twistlers in opposite directions and coil the ends of the sections of a transverse stay wire around the strand wires, and means for limiting the actuating movement of said rack-bars in both directions, substantially as described.

15. In a wire fence machine, a fence forming revoluble drum having at intervals longitudinally movable rack-bars arranged in pairs, with the rack-bars of each pair longitudinally movable in opposite directions, slotted twistlers, each twister having a driving wheel and fixedly arranged in pairs and mounted with the driving wheels of each pair of twistlers in mesh with a pair of rack-bars, each twister having an acting end face adapted to engage the ends of the sections of a transverse stay wire and coil said ends around the strand wires, and means for actuating the rack-bars of a pair successively and in opposite directions as the drum is revolved, for the opposite movements of the two companion rack-bars to revolve the pair of companion twistlers in opposite directions and coil the ends of the transverse stay wire

around the strand wires, substantially as described.

16. In a wire fence machine, a revoluble fence forming drum, twister mechanism mounted thereon, said mechanism comprising opposite rows of twister heads arranged in pairs, each twister head having an acting end face adapted to engage the ends of the sections of a transverse stay wire and coil said ends around the strand wires, a reel for drawing the running wires of the fence fabric and the completed fabric about and away from said drum, and a single means for revolving both the drum and the reel, substantially as described.

17. A wire fence machine, comprising a revoluble drum, a series of opposite rows of twisting devices arranged on said drum, each twisting device having an acting end face adapted to engage the ends of the sections of a transverse stay wire and coil said ends around the strand wires, oppositely moving power devices engaging the twistlers of each independent row of the pairs of twisting devices, and means for imparting movement in opposite directions to each pair of power devices at a given point in the movement of said drum for rotating the twistlers in the companion rows of twistlers in opposite directions and in succession, substantially as described.

18. In a wire fence machine, a revoluble drum, means for drawing the running wires of the fence fabric circumferentially over and from said drum, twistlers mounted in opposite rows on said drum, each row containing a plurality of twistlers, and each twister having an acting end face adapted to engage the ends of the sections of the transverse stay wire and coil said ends around the running wires, uniting the running wires with the sections of the transverse stay wire extending longitudinally of the drum, substantially as described.

19. In a wire fence machine, a revoluble drum, a reel for drawing the running wires of the fabric over and away from said drum, a single means for driving said drum and reel, twistlers mounted in opposite rows on said drum, each row containing a plurality of twistlers, and each twister having an acting end face adapted to engage the ends of the sections of a transverse stay wire and coil said ends around the running wires, uniting the running wires with the sections of the transverse stay wire, substantially as described.

20. In a wire fence machine, a revoluble drum, twistlers mounted in opposite rows on the surface of the drum and in rows around the drum and also longitudinally of the drum, each row containing a plurality of twistlers and each twister having an acting end face adapted to engage the ends of the sections of a transverse stay wire and coil

5 said ends around the strand wires, mechanism carried by the drum and movable longitudinally beneath the twisters and adapted to actuate the twisters of opposite rows in succession at predetermined intervals and in 10 opposite directions of rotation to coil the ends of the transverse stay wire sections around the strand wires, and means for inaugurating the movement of said mechanism at the same point in the travel of said 15 twisters, substantially as described.

21. In a wire fence machine, a revoluble drum comprising a revoluble shaft, a head secured to said shaft at or near each end, a 15 series of longitudinal bars attached at their opposite ends to said heads, twisters mounted in opposite rows on said bars, each row containing a plurality of twisters and each twister having an acting end face adapted to 20 engage the ends of the sections of a transverse stay wire and coil said ends around the strand wires, and mechanism carried by said bars and movable longitudinally beneath said twisters at predetermined intervals to 25 give an opposite direction of rotation to companion twisters in each opposite row of twisters to coil the ends of the transverse stay wire sections around the strand wires, substantially as described.

30 22. In a wire fence machine, a revoluble drum comprising a revoluble shaft, a head secured to said shaft at or near each end, a series of longitudinal bars attached at their opposite ends to said heads, twisters mounted 35 in opposite rows on said bars, each row containing a plurality of twisters and each twister having an acting end face adapted to engage the ends of the sections of a transverse stay wire and coil said ends around the 40 strand wires, mechanism carried by said bars and movable longitudinally beneath said twisters at predetermined intervals to give an opposite direction of rotation to companion twisters in each opposite row of 45 twisters to coil the ends of the transverse stay wire sections around the strand wires, and means for inaugurating the opposite movement of such mechanism at the same 50 point in the travel of said rows of twisters, substantially as described.

23. In a wire fence machine, a revoluble drum, twisters mounted in opposite rows on the surface of the drum and around and also longitudinally of the drum, each row of 55 twisters containing a plurality of twisters and each twister having an acting end adapted to engage the ends of the sections of a transverse stay wire and coil said ends around the strand wires, and means for in- 60 augurating the movement in opposite directions of each opposite longitudinal row of twisters at the same point in their travel, substantially as described.

24. In a wire fence machine, a revoluble 65 drum, twisters mounted in opposite rows on

the surface of the drum and around and also longitudinally of the drum, each row of twisters containing a plurality of twisters and each twister having an acting end adapted to engage the ends of the sections of a 70 transverse stay wire and coil said ends around the strand wires, each twister having a driving wheel, and means for inaugurating the movement in opposite directions of each opposite longitudinal row of twisters at the 75 same point in their travel, substantially as described.

25. In a wire fence machine, a revoluble drum, twisters mounted in opposite rows on the surface of the drum and around and also 80 longitudinally of the drum, each row of twisters containing a plurality of twisters and each twister having an acting end adapted to engage the ends of the sections of a transverse stay wire and coil said ends 85 around the strand wires, each twister having a driving wheel, and mechanism disposed beneath each opposite row of twisters and in mesh with the twister wheels of each opposite row adapted, at a given point in the 90 movement of the drum, to be moved longitudinally for imparting opposite rotation to the companion twisters in each opposite row of twisters, substantially as described.

26. A wire fence machine, comprising a 95 revoluble drum, a series of opposite rows of twisting devices arranged on said drum, each twisting device having an acting end face adapted to engage the ends of the sections of a transverse stay wire and coil said ends 100 around the strand wires, oppositely moving power devices engaging the twisters of each independent row of the pair of twisting devices, and means for imparting a forward and return movement in opposite directions to each pair of power devices at a given point in the movement of said drum for rotating the twisters in the companion rows of twist- 105 ers in opposite directions and in succession, substantially as described.

27. In a machine for the manufacture of wire fabric, comprising a revoluble and supporting shaft, a series of longitudinal supports mounted on the shaft, opposite rows of twisting devices having toothed peripheries 110 and mounted for rotation on each of said supports, each twisting device having an acting end face adapted to engage the ends of the sections of a transverse stay and coil said ends around the strand wires, gearing mesh- 115 ing with said opposite row of twisters and operating for revolving companion twisters in two adjoining rows of twisters in opposite directions to coil the ends of the transverse stay wire sections around the strand wires, 120 and means for actuating said gearing in op- 125 posite direction for the two adjacent rows of twisters, substantially as described.

28. In a machine for the manufacture of wire fabric, comprising a supporting shaft, a 130

series of longitudinal supports mounted on the shaft, opposite rows of twisting devices having toothed peripheries and mounted for rotation on each of said supports, each twisting device having an acting end face adapted to engage the ends of the sections of a transverse stay and coil said ends around the strand wires, gearing meshing with said opposite row of twistlers and operating for revolving companion twistlers in two adjoining rows of twistlers in opposite directions to coil the ends of the transverse stay wire sections around the strand wires, and means for actuating said gearing in opposite directions for the two adjacent rows of twistlers, substantially as described.

29. In a wire fence machine, the combination of a revoluble shaft, twister supports fixedly mounted on said shaft, and revoluble twisting devices journaled in said supports having their axes disposed in line with the travel of wires fed thereto, said twisting devices arranged in pairs of opposite rows, each row comprising a plurality of twisters and each twister having an acting end face adapted to engage the ends of the sections of a transverse stay and coil said ends in opposite directions around the strand wires, and the twisters of one row having an opposite direction of rotation to the twisters of the adjacent row in coiling the ends of the transverse stay wire sections around the strand wires, substantially as described.

20

25

30

30. A device of the class described, comprising a revoluble support, twisting devices arranged in opposite pairs and longitudinal rows on said support, each twisting device having an acting end face adapted to engage the ends of the sections of a transverse stay wire and coil said ends around the strand wires, and means carried by said support and oppositely movable longitudinally beneath the twisters of each longitudinal row adapted to actuate the companion rows of twistlers in opposite directions at predetermined intervals during the rotation of said support, substantially as described.

31. A wire fence machine, comprising a revolving frame, a series of twisting devices carried thereby, with the twisting devices of the series opposite each other and each twisting device adapted to engage the ends of the sections of a transverse stay wire and coil said ends around the strand wires, the arrangement of the frame and twisters being such that as the frame is revolved each companion pair of twisters will be actuated in opposite directions to coil the ends of the transverse stay wire sections the width of the fabric around the strand wires, substantially as described.

32. A machine for the manufacture of wire fabric, comprising a revolving frame, means for feeding loose strand and sectional stay wires to said frame, twisting devices ar-

ranged in opposite pairs for engaging the ends of the sections of the transverse stay wires and coiling said ends around the strand wires as the twisting devices successively move into the path of the wires during the rotating of the frame, said twisters arranged to revolve in opposite directions and different from the rotation of said frame for coiling the ends of the transverse stay wire sections around the strand wires and delivering a finished fabric during the rotation of the frame, as and for the purposes set forth. 70 75

33. A machine for the manufacture of wire fabric, comprising a revolving frame, means for feeding wires to said frame longitudinally and transversely, twisting devices arranged in opposite pairs for engaging the ends of the sections of said transverse wires, said twistets arranged in pairs to revolve in opposite directions and in directions different from the rotation of said frame for coiling the ends of the transverse stay wire sections around the strand wires during the rotation of the revolving frame, substantially as described. 80 85

34. In a machine of the class described, a revoluble frame, a series of revolubly supported twisting devices in pairs opposite each other and journaled on said frame, each twisting device of each series having an acting end face adapted to engage the end of the sections of a transverse stay wire and coil said ends around the strand wires, a series of opposite reciprocally disposed rack-bars engaging the series of opposite twisters, a cylindrical member disposed at one end of the frame, a cam ring attached to the inner face of the member, and a roller on each rack-bar and engaging the cam ring, for the purposes set forth

35. A wire fence machine, comprising a rotating frame, a series of opposite rows of twisting devices suitably arranged on said frame, each twisting device of each row having an acting end face adapted to engage the ends of the sections of a transverse stay wire and coil said ends around the strand wires, each opposite row of twistets successively actuated during the rotation of said frame, the companion pair of twistets rotating in opposite directions for continuously weaving together a series of wires engaging said twistets by coiling the ends of the transverse stay wire sections around the strand wires, substantially as described. 110 115 120

36. A wire fence machine, comprising a rotating frame, a series of opposite rows of twisting devices arranged on said frame, each twisting device of each row having an acting end face adapted to engage the ends of the sections of a transverse stay wire and coil said ends around the strand wires, and mechanism arranged in such manner that as the frame is rotated one or more of the opposite rows of the series of twisters will be actuated. 130

for the pair of companion twisters of the two opposite rows to revolve in opposite directions during a partial rotation of said frame, for coiling the ends of the transverse stay wire sections around the strand wires, substantially as described.

37. A wire fence machine, comprising a rotating frame, a series of opposite rows of twisting devices arranged in pairs in said frame, each twisting device of each row having an acting end face adapted to engage the ends of the sections of a transverse stay and coil said ends around the strand wires, and power devices coacting with each row of twisters during the rotation of said frame arranged in a manner to revolve the pairs of twisters of each opposite row of twisting devices in opposite directions and to engage and actuate only a few of said rows, the remaining rows being substantially inoperative until moved into the path of the power devices, substantially as described.

38. A wire fence machine, comprising a rotary frame, devices in opposite pairs carried thereby for engaging the ends of the sections of a series of transverse stay wires and coiling said ends around the strand wires to interlock said strand and transverse wires and form a square mesh during the rotation of the frame, and means for actuating the aforesaid pair of companion devices in opposite directions in coiling the ends of the transverse stay wire sections around the strand wires, substantially as described.

39. A wire fence machine, comprising a rotary frame, a series of twisters arranged in pairs and in opposite rows across and circumferentially upon said frame, each twister having an acting end face adapted to engage the ends of the section of a transverse stay wire and coil said ends around the strand wires, and means for actuating the pairs of twisters of each companion row in opposite directions during the rotation of the frame to simultaneously and successively operate in opposite directions the pairs of each companion row of twisters, as and for the purposes set forth.

40. In a wire fence machine, a fence forming drum having at intervals opposite longitudinally movable rack bars arranged in pairs, slotted twisters arranged in pairs, each twister having a driving wheel mounted in mesh with a rack-bar of each pair of oppositely movable rack-bars, each twister having an acting end face adapted to engage the ends of the sections of a transverse stay wire and coil said ends around the strand wires, and means for revolving the drum and actuating each pair of rack-bars in opposite directions while the drum is in motion, substantially as described.

41. In a wire fence machine, a fence forming drum having at intervals opposite lon-

gitudinally movable rack-bars arranged in pairs, slotted twisters arranged in pairs, each twister having a driving wheel mounted in mesh with a rack-bar of each pair of oppositely movable rack-bars, each twister having an acting end face adapted to engage the ends of the sections of a transverse stay wire and coil said ends around the strand wires, means for revolving the drum and actuating each pair of rack-bars in opposite directions while the drum is in motion, and means for returning each pair of rack-bars in opposite directions successively while the drum is in motion, substantially as described.

42. In a wire fence machine, a fence forming drum having at intervals opposite longitudinally movable rack-bars arranged in pairs, slotted twisters arranged in pairs, each twister having a driving wheel mounted in mesh with a rack-bar of each pair of oppositely movable rack-bars, each twister having an acting end face adapted to engage the ends of the sections of a transverse stay wire and coil said ends around the strand wires, means for revolving the drum and actuating each pair of rack bars in opposite directions while the drum is in motion, and means for limiting the actuating movement in opposite directions of each pair of rack bars, substantially as described.

43. In a wire fence machine, a fence forming revoluble drum having at intervals longitudinally extending rows of twister brackets each formed with a pair of oppositely located slotted plates, a pair of longitudinally oppositely movable rack bars mounted in each longitudinal row of twister brackets, a pair of slotted and toothed opposite twisters, each twister having a driving wheel and mounted in each bracket in mesh with a rack bar of said pair of rack bars, each twister having an acting end face adapted to engage the ends of the sections of a transverse stay wire and coil said ends around the strand wires, and means for actuating the rack bars of each pair in opposite directions during the movement of the drum and revolve a pair of twisters in opposite directions, for coiling the ends of the transverse stay wire sections around the strand wires, substantially as described.

44. In a wire fence machine, a fence forming revoluble drum having at intervals opposite longitudinally movable rack bars in pairs, slotted twisters in opposite pairs, each twister having a driving wheel mounted in mesh with a rack bar of the pair of rack bars, and each twister having an acting end face adapted to engage the ends of the sections of a transverse stay wire and coil said ends around the strand wires, and means for actuating the pair of rack-bars in opposite directions while the drum is in motion, for revolving the pair of twisters in opposite di-

rections and coiling the ends of the sections of a stay-wire around the strand wires, substantially as described.

45. In a wire fence machine, a fence forming revoluble drum having at intervals opposite longitudinally movable twister actuating devices in pairs, slotted twisters in opposite pairs, each twister having a driving wheel mounted in mesh with said twister actuating devices, each twister having an acting end face adapted to engage the ends of the sections of a transverse stay wire and coil said ends around the strand wires, and means disposed at alternate ends of adjacent pairs of twister actuating devices adapted to impart opposite movement thereto for revolving the pairs of twisters in opposite directions and coiling the ends of the transverse stay wire sections around the strand wires, substantially as described.

46. In a wire fence machine, a fence forming revoluble drum having at intervals opposite longitudinally movable twister actuating devices in pairs, slotted twisters arranged in pairs, each twister having a driving wheel, and disposed in longitudinal rows in mesh with the pair of actuating devices and each twister having an acting end face adapted to engage the ends of the sections of a transverse stay wire and coil said ends around the strand wires, and means disposed at alternate ends of adjacent opposite rows of twisters adapted to be successively actuated at the same point in their travel, for imparting opposite movement to said actuating devices and revolving said twisters through said devices in opposite direction for the pairs of twisters, and coiling the ends of the transverse sectional stay wire around the strand wires, substantially as described.

47. In a wire fence machine, a revoluble drum, a series of opposite longitudinal rows of twisters mounted on said drum in pairs, each twister having an acting end face to engage the ends of the sections of a transverse stay wire and coil said ends around the strand wires, mechanism movable longitudinally beneath each row of twisters and in opposite directions and in mesh with the twisters of each pair, for revolving the twisters of a pair in opposite directions and coiling the ends of the transverse stay wire sections around the strand wires, and means disposed at alternate ends of adjacent opposite rows of twisters adapted at intervals to operate the aforesaid mechanism, substantially as described.

48. In a wire fence machine, a revoluble drum, a series of opposite longitudinal rows of twisters mounted on said drum in pairs, each twister having an acting end face to engage the ends of the sections of a transverse stay wire and coil said ends around the strand wires, mechanism movable longitudinally beneath each row of twisters and in opposite directions and in mesh with the twist-

ers of each pair for revolving the twisters of a pair in opposite directions and coiling the ends of the transverse stay wire sections around the strand wires, and means disposed at alternate ends of adjacent opposite rows of 70 twisters adapted to be successively actuated for imparting rotary movement in opposite directions to the pairs of twisters of the longitudinal rows of twisters in succession and in manner specified, substantially as described. 75

49. In a wire fence machine, a revoluble drum, twisters mounted on the drum in opposite pairs and in rows around the drum and also longitudinally of the drum, each twister of each row having an acting end face adapted to engage the ends of the sections of a transverse stay wire and coil said ends around the strand wires, independent driving means for each longitudinal opposite row of twisters, said driving means operating to revolve 80 the twisters of each pair in the opposite row of twisters in opposite directions, for coiling the ends of the transverse stay wire sections around the strand wires, and power devices at alternate ends of adjacent twisters of opposite rows of twisters adapted to be intermittently and successively put in motion for transmitting opposite motion to the pairs of twisters of the rows of opposite twisters in 85 succession and in the manner specified, substantially as described.

50. In a machine for making wire fabric, the combination with a rotary drum, of a series of twisters distributed around the drum, each twister having an acting end face 100 adapted to engage the ends of the sections of a transverse stay wire and coil said ends around the strand wires, with the twisters arranged in pairs for each series, and means for operating the pairs of twisters in each series in opposite directions to form reverse 105 coils for the ends of the transverse stay wire sections around the strand wires, substantially as described.

51. In a machine for making wire fabric, 110 the combination with a rotary drum, of a series of twisters distributed around the drum, each twister having an acting end face adapted to engage the ends of the sections of a transverse stay wire and coil said ends 115 around the strand wires, with the twisters arranged in pairs for each series, and means for operating the pairs of twisters in each series in opposite directions to form reverse coils for the ends of the transverse stay wire. 120 sections around the strand wires, said means inaugurating the opposite rotation of the twisters of each pair of twisters at the same point in their travel, substantially as described.

52. In a machine for making wire fabric, the combination with a rotary drum, of a series of sets of twisters distributed around the drum, each set comprising a pair of twisters and each twister having an acting 125

end face adapted to engage the ends of the sections of a transverse stay wire and coil said ends around the strand wires, means for guiding the strand wires and the sections of the transverse stay wire to the pair of twist-
ers of each set of twist-
ers, and means for operating each pair of twist-
ers of the different sets of twist-
ers in different directions to form reverse coils for the ends of the transverse stay wire sections around the strand wires, substantially as described.

53. In a machine for making wire fabric, the combination with a weaving drum, of weaving mechanism mounted thereon and arranged to be operated by the movement of the drum, said weaving mechanism comprising opposite rows of twist-
ers, with the twist-
ers of the opposite rows arranged in pairs and each twister having an acting end adapted to 20 engage the ends of the sections of a transverse stay wire and coil said ends around the strand wires, the twist-
ers of each pair of twist-
ers revolving in opposite directions in coiling the ends of the transverse stay wire sections 25 around the strand wires, substantially as described.

54. In a wire fence machine, the combination of a revoluble shaft, a carrier fixedly mounted and revolving with the shaft, a plurality of coiling mechanisms mounted on and revoluble with the carrier and arranged in opposite series, each opposite series comprising a plurality of twister heads, each twister head having an acting end face adapted to engage 30 the ends of the sections of a transverse stay wire and coil said ends around the strand wires, a pinion for each twister head, a rack bar common to all the pinions of a series of twister heads in each row of twister heads, 35 the rack bars for the pairs of twister heads in each opposite row having a reciprocating movement in opposite directions, and means operative from the revolving of the carrier to reciprocate the pair of rack bars of companion 40 rows of twist-
ers in opposite directions and successively actuate in opposite directions the twister heads of companion rows of the different series of twister heads, substantially as described.

55. In a wire fence machine, the combination of a continuously revoluble carrier, a plurality of coiling mechanisms mounted on and revoluble with the carrier and arranged in opposing series, each series comprising a 55 plurality of twister heads in pairs, each twister head having an acting end face adapted to engage the ends of the sections of a transverse stay wire and coil said ends around the strand wires, and each twister head having a longitudinal slot for the passage of a strand wire to the center of a twister head, and each twister head having thereon a driving pinion, a rack bar common to all of the pinions of a series of opposite twister heads, 60 and means for reciprocating in opposite di- 65

rections the rack bars of two companion series of twister heads to rotate the two series of twister heads in opposite directions, substantially as described.

56. A device of the class described, comprising a shaft, a series of twister supports mounted to revolve with said shaft, revolving twister devices mounted in rows and opposite each other in pairs on said supports, each twister device having an acting end 70 adapted to engage the ends of the sections of a transverse stay wire and coil said ends around the strand wires, and means longitudinally movable in opposite directions through said supports and coacting with said 75 twisters for intermittently rotating the two twisters of each pair of said twisters in opposite directions during the rotation of the shaft and supports, substantially as described.

57. A device of the class described, comprising a shaft adapted to be continuously revolved, a series of twister supports mounted on said shaft, slotted twisting devices journaled on said supports and mounted in 80 opposite pairs, each twisting device having an acting end face adapted to engage the ends of the sections of a transverse stay wire and coil said ends around the strand wires, and twister actuating devices arranged in pairs 85 and movable in opposite directions through said supports and beneath the opposite pairs of twisters for revolving the twisters in opposite directions and coiling the ends of the transverse stay wire sections around the 90 strand wires, and power devices disposed at one end of the supports adapted to drive the twister actuating devices in opposite directions, substantially as and for the purpose 95 specified.

58. In a machine for making wire fabric, the combination with a pair of traveling twist-
ers arranged opposite each other and having opposite directions of rotation, each twister having an acting end face adapted to 100 engage the ends of the sections of a trans-
verse stay wire and coil said ends around the strand wires, of means for rotating the pair of twist-
ers in different directions during their travel, substantially as described.

59. In a machine for making wire fabric, the combination with a pair of traveling twist-
ers arranged opposite each other and having opposite directions of rotation, each twister having an acting end face adapted to 110 engage the ends of the sections of a trans-
verse stay wire and coil said ends around the strand wires, of a pair of reciprocating racks, one rack geared with each twister, and each rack having a reciprocating movement in op- 115 posite directions, for giving the two twist-
ers opposite directions of travel in coiling the ends of the transverse stay wire sections around the strand wires, and a cam arranged 120 to oppositely reciprocate the two racks to ro- 125

tate the two twistlers in opposite directions during their travel, substantially as described.

60. In a machine for making wire fabric, the combination with a pair of twistlers arranged opposite each other and mounted to travel in an endless orbit, each twister having an acting end face to engage the ends of the sections of a transverse stay wire and coil 13 said ends around the strand wires, of a pair of racks, one rack geared to each twister, the two racks having a reciprocating movement in opposite directions for actuating the twistlers to coil the ends of the transverse stay wire sections around the strand wires, and means for reciprocating the two racks to rotate the two twistlers in opposite directions during the travel thereof, substantially as described.
- 23 61. In a machine for making wire fabric, the combination with a pair of rotary twistlers mounted opposite each other to travel in an endless orbit, each twister having an acting end face to engage the ends of the sections of a transverse stay wire, of a pair of racks, one rack geared to each twister, the racks having reciprocating movements in opposite directions to rotate the twistlers in opposite directions and coil the ends of the 25 transverse stay wire sections around the strand wires, and a fixed cam operatively related to the two racks to reciprocate the racks in opposite directions during the travel of the twistlers, substantially as described.
- 55 62. In a machine for making wire fabric, the combination with a series of opposite rows of traveling twistlers arranged in pairs, each twister having an acting end face adapted to engage the ends of the sections of 40 a transverse stay wire and coil said ends around the strand wires, of mechanism disposed beneath each opposite row of twistlers and in operative connection with the same and actuating the twistlers of companion 45 rows in opposite directions for coiling the ends of the transverse stay wire sections around the strand wires, and means disposed at opposite ends of alternate rows of opposite twistlers adapted to operate the aforesaid 50 mechanism of adjacent rows in reverse directions, substantially as described.

63. In a machine for making wire fabric, the combination with a series of opposite rows of traveling twistlers arranged in pairs, each twister having an acting end face to engage the ends of the sections of a transverse stay wire and coil said ends around the strand wires, of means for moving opposite rows of twistlers in unison and in opposite directions 60 of travel, for the twistlers to operate and coil the ends of the transverse stay wire sections around the strand wires, and means disposed at opposite ends of alternate rows of twistlers adapted to impart movement to 65 said rows of twistlers in succession and oper-

ate the twistlers of adjacent rows in opposite directions, substantially as described.

64. In a machine for making wire fabric, the combination with a series of opposite twistlers mounted in pairs to travel in an endless orbit, each twister having an acting end face to engage the ends of the sections of a transverse stay and coil said ends around the strand wires, of means operated during the travel of the twistlers for operating one series 70 of the same in one direction and another series of the same in opposite direction to form reverse twists in coiling the ends of the transverse stay wire sections around the strand wires, substantially as described.

80 65. In a machine for making wire fabric, the combination with a series of opposite twistlers mounted in pairs to travel in an endless orbit, each twister having an acting end face to engage and coil the ends of the 85 sections of a transverse stay wire around the strand wires, of means for operating alternate rows of twistlers in opposite directions to form reverse twists in coiling the ends of the transverse stay wire sections around the 90 strand wires, substantially as described.

66. In a machine for making wire fabric, the combination with several sets of opposite twistlers arranged in pairs, each twister having an acting end face to engage and coil 95 the ends of the sections of a transverse stay around the strand wires, of means for operating adjacent sets of twistlers in different directions to form reverse twists in coiling the ends of the transverse stay wire section 100 around the strand wires, substantially as described.

67. In a machine for making wire fabric, the combination with several sets of opposite twistlers mounted in pairs to travel in 105 unison, each twister having an acting end face to engage the ends of the sections of a transverse stay wire and coil said ends around the strand wires, of means for operating adjacent sets of twistlers in opposite 110 directions to form reverse twists during the travel of the twister in coiling the ends of the transverse stay wire sections around the strand wires, substantially as described.

68. In a machine for making wire fabric, the combination of several sets of opposite twistlers mounted in pairs to travel in an endless orbit, each twister having an acting end face to engage and coil the ends of the sections of a transverse stay wire around the 120 strand wires, of means for operating alternate sets of twistlers in opposite directions during the travel thereof in coiling the ends of the transverse stay wire sections around the strand wires, substantially as described.

125 69. In a wire fence machine, the combination of mechanism for continuously feeding forward a plurality of strand wires, a revolute carrier over which the strand wires lead and in unison with which the strand wires 130

travel, a plurality of opposite rows of twister heads, each row arranged in series and mounted on the revoluble carrier, each series comprising a number of twister heads in pairs corresponding to the number of strand wires, and each twister head having a longitudinal slot for the passage of the strand wires to the center of the twister head, and each twister having an acting end adapted to engage the overlapping ends of the sections of a transverse stay wire and oppositely coil the ends around the strand wires, a pinion for each twister head of the series in each row, a rack-bar common to all the pinions in a series of twister heads for each row, and means for reciprocating the rack-bars of companion rows simultaneously in opposite directions and revolving the twister heads of the two rows in opposite directions as the carrier travels forward, substantially as described.

70. In a wire fence machine, the combination of mechanism for continuously feeding forward a plurality of strand wires, a revoluble carrier over which the strand wires lead and in unison with which the strand wires travel, a plurality of opposite rows of twister heads each row arranged in series and mounted on the revoluble carrier, each series comprising a number of twister heads in pairs corresponding to the number of strand wires, and each twister head having a longitudinal slot for the passage of the strand wires to the center of the twister head, and each twister having an acting end adapted to engage the overlapping ends of the sections of a transverse stay wire and oppositely coil the ends around the strand wires, a pinion for each twister head of the series in each row, a rack-bar common to all the pinions in a series of twister heads for each row, a roller on the end of each rack bar, and a fixed head having a cam groove receiving the roller for reciprocating two companion rack bars in opposite directions and revolving the twister heads of two companion rows in opposite directions, substantially as described.

71. In a wire fence machine, the combination of mechanism for continuously feeding forward a plurality of strand wires, a revoluble carrier over which the strand wires lead and in unison with which the strand wires travel, a plurality of opposite rows of twister heads each row arranged in series and mounted on the revoluble carrier, each series comprising a number of twister heads in pairs corresponding to the number of strand wires, and each twister head having a longitudinal slot for the passage of the strand wires to the center of the twister head, and each twister having an acting end adapted to engage the overlapping ends of the sections of a transverse stay wire and oppositely coil the ends around the strand wires, a pinion for each twister head of the series in each row, a rack-bar common to all the pinions in a series of

twister heads for each row, a roller on the end of each rack bar, a fixed head having a cam groove receiving the roller for reciprocating two companion rack bars in opposite directions and revolving the twister heads of two companion rows in opposite directions, and means independent of the revoluble carrier for crimping the strand wires, substantially as described.

72. In a machine for making wire fabric, the combination with a revoluble support and a revoluble stay carrier movable in unison, said carrier adapted to receive the sections of a transverse stay wire and deliver the same to the support, of wire connecting mechanism mounted on the support, said wire connecting mechanism comprising twisting devices in opposite rows and in pairs, each twisting device having an acting end face adapted to engage the ends of the sections of the transverse stay wire and coil said ends around the strand wires, substantially as described.

73. In a machine for making wire fabric, the combination with a revoluble support and a revoluble stay carrier movable in unison, the stay carrier adapted to receive the sections of a transverse stay wire and deliver the same to the support, of twisting mechanism mounted on the support, said mechanism comprising a plurality of opposite rows of twister heads in pairs, each twister head having an acting end face adapted to coil the ends of the sections of the transverse stay wire around the strand wires, substantially as described.

74. In a machine for making wire fabric, the combination with a revoluble support and a revoluble stay carrier movable in the same direction, the stay carrier adapted to receive the sections of a transverse stay wire and deliver the same to the support, of twisters mounted in opposite rows and in pairs on the support, each twister having an acting end face adapted to engage the ends of the sections of the transverse stay wire and coil said ends around the strand wires, and means for leading the strand wires to the twisters, substantially as described.

75. In a machine for making wire fabric, the combination with supporting means for a plurality of line wires, of a revoluble stay carrier arranged to move the sections of a transverse stay wire sidewise to present the several sections to said line wires, and twisting means for connecting the sections of the transverse stay wire and the line wires without interrupting the movement of the transverse stay wire sections, said twisting means comprising opposite rows of twister heads arranged in pairs, each twister head having an acting end face adapted to engage the ends of the sections of the transverse stay wire and coil said ends around the line wires, substantially as described.

76. A machine for making wire fabric, comprising a revoluble support, twisters arranged in parallel opposite rows and in pairs on the support and adapted to receive line wires, each twister having an acting end face adapted to engage the sections of a transverse stay wire and coil said ends around the line wires, and means for feeding the sections of the transverse stay wire to the support, for the ends of the transverse stay wire sections to be coiled around the strand wires by the twisters, substantially as described.

77. A machine for making wire fabric, comprising a revoluble support, several sets of opposite rows of wire twisters arranged in pairs and mounted on the support and adapted to receive line wires, each twister having an acting end face adapted to engage the ends of the sections of a transverse stay wire and coil said ends around the strand wires, means for feeding the sections of the transverse stay wire to the support during the movement of the latter for the twisters to coil the ends of the stay wire sections around the line wires, and means for operating the opposite row of twisters to connect the line wires and the transverse stay wire sections, substantially as described.

78. In a machine for making wire fabric, the combination with a rotary support, of means for advancing a series of line wires, means for feeding the sections of a transverse stay wire across the series of line wires, with the ends of the stay wire sections overlapping the line wires, and mechanism for connecting the sections of the transverse stay and the line wires, said mechanism comprising opposite rows of twisting devices arranged in pairs, each twisting device having an acting end face to engage the ends of the sections of the transverse stay wire and coil said ends around the strand wires, substantially as described.

79. In a machine for making wire fabric, the combination with a rotary support, of means for guiding a series of line wires over the support, means for feeding the sections of a transverse stay wire across the line wires over the support, with the ends of the transverse stay wire section overlapping the line wires, a wire connecting mechanism, including a circumferential series of opposite twisters in pairs, carried by the rotary support and moving in the same plane to connect successive transverse stay wire sections to a line wire by coiling the ends of the transverse stay wire sections around the line wire, substantially as described.

80. A machine for the manufacture of wire fabric, comprising a revolving frame, means for feeding line wires and the loose sections of transverse stay wires to said frame, twisting devices for engaging said wires as they successively move into the path of the wires dur-

ing the rotating of the frame, said twisting devices arranged in opposite rows and in pairs on the frame, for the opposite pairs to revolve in opposite directions, one row from the other, and different from the rotation of said frame, each twister having an acting end face adapted to engage the ends of the sections of the transverse stay wire and coil said ends around the strand wires and deliver a finished fabric during the rotation of the frame, as and for the purposes set forth.

81. A machine for making wire fence, comprising a revoluble frame, a plurality of twisters arranged in a plurality of opposite rows on said frame, with the twisters of the rows in pairs and adapted to retain and advance a series of strand wires, each twister having an acting end face to engage the ends of the sections of a transverse stay wire and coil said ends around the strand wires, and means for feeding the sections of the transverse stay wire to the companion twisters of opposite rows, as the rows of twisters successively follow each other in the movement of the revoluble frame, for the twisters to act and coil the ends of the stay wire sections around the strand wires, substantially as described.

82. A machine for making wire fence, comprising a revoluble frame, several opposite sets of wire twisters mounted in pairs on said frame adapted to receive and advance strand wires, each twister having an acting end face to engage and coil the ends of the sections of a transverse stay wire around the strand wires, means for feeding the sections of a transverse stay wire to each set of opposite twisters, as the rows of twisters successively follow each other in the movement of the frame, for the twisters to act and coil the ends of the stay wire sections around the strand wires, and means for operating the twisters to coil the sections of the stay wire around the strand wires in transit, substantially as described.

83. In a wire fence machine, a fence forming drum, means for holding the line wires of the fence fabric circumferentially on said drum, and twisters mounted in opposite pairs and in rows on said drum, each twister having an acting end face to engage and coil the ends of the sections of a transverse stay wire around the running wires, and the twisters operating during the movement of the drum to unite the running wires with the sections of the transverse stay wire extending longitudinally of the drum by coiling the ends of the transverse stay wire sections around the running wires, substantially as described.

84. In a wire fence machine, a revoluble fence forming drum, twister mechanism mounted thereon and operating during the movement thereof, said twister mechanism

- comprising opposite rows of twisters arranged in pairs, each twister having an acting end face to engage and coil the ends of the sections of a transverse stay wire around the sections of a transverse stay wire 65
- 5 the running wires, a reel for drawing the running wires of the fence fabric and the completed fabric about and away from said drum, and means for revolving both the drum and the reel, substantially as described.
- 10 85. In a wire fence machine, a revoluble drum, means for continuously drawing the running wires of the fence fabric circumferentially over and from said drum, and opposite rows of twisters mounted in pairs on said 70 drum in position to engage said running wires and to engage the ends of the sections of a transverse stay wire and unite the running wires and the transverse stay wire sections extending longitudinally of the drum 75
- 15 20 by coiling the ends of the transverse stay wire sections around the running wires, substantially as described.
86. In a wire fence machine, a revoluble drum, a reel for drawing the running wires of the fabric over and away from said drum, means for continuously driving said drum 80 and reel, and rows of twisters oppositely mounted in pairs on said drum in position to engage said running wires and the ends of the 85 sections of a transverse stay wire and unite the running wires and the transverse stay wire sections by coiling the ends of the sections around the running wires, substantially as described.
- 30 87. In a machine for making wire fabric, the combination with a rotary drum, of a series of wire connecting devices carried thereby, said series of wire connecting devices comprising opposite rows of twisters arranged 90
- 35 40 in pairs, each twister having an acting end face to engage the ends of the sections of a transverse stay wire and coil said ends around the strand wires, means for intermittently actuating the twisters of opposite 95 rows in different directions during the rotation of the drum and at the same point in their travel, a feeder mounted above the drum for advancing a plurality of wires to form the sections of a transverse stay wire, 100
- 45 50 and means for advancing the sections of the transverse stay wire from the feeder to the drum and in position for the twisters of the opposite rows to coil the ends of the transverse stay wire section around the strand 105 wires, substantially as described.
- 55 88. In a machine for making wire fabric, the combination with a rotary drum, of opposite rows of twisters mounted in pairs thereon, each twister having an acting end 110 face to engage and coil the ends of the sections of a transverse stay wire around the strand wires, means for leading the line wires to the twisters, and a stay carrier co-operating with the drum and operating to re-
- ceive and deliver the sections of the transverse stay wire in position for the ends of the transverse stay wire section to be coiled around the strand wires by the opposite twisters, substantially as described.
89. In a machine for making wire fabric, 70 the combination with a rotary drum equipped with opposite sets of twisters in pairs, each twister having an acting end face to engage and coil the ends of the sections of a transverse stay wire around the line wires, of means 75 for advancing a plurality of line wires with the twisters, and means for moving the sections of the transverse stay wire sidewise to present the sections to the line wires and in position for the ends of the transverse stay 80 wire sections to be coiled around the line wires, substantially as described.
90. In a machine for making wire fabric, the combination with a rotary drum equipped with opposite sets of twisters in pairs, each 85 twister having an acting end face to engage and coil the ends of the sections of a transverse stay wire around the line wires, of means 90 for leading line wires to the twisters, and a traveling carrier operating to receive the sections of the transverse stay wire and present said sections to the line wires in position for the opposite set of twisters to coil the ends of said sections around the strand 95 wires, substantially as described.
91. In a machine for making wire fabric, the combination with a rotary drum equipped with a plurality of opposite sets of wire connecting mechanisms, each mechanism comprising a row of twisters and each twister 100 having an acting end face to engage and coil the ends of the sections around the line wires, substantially as described.
92. In a machine for making wire fabric, the combination with a rotary drum equipped 105 with several opposite sets of wire connecting mechanisms, said mechanisms comprising opposite rows of twisters arranged in pairs, each twister having an acting end face to engage and coil the ends of the sections of a 110 transverse stay wire around the line wires, means for leading line wires to the drum, and a stay carrier associated with said drum and operating to receive and deliver the transverse stay wire sections to the opposite rows 115 of twisters, for the twisters to act and coil the ends of the transverse stay wire sections around the line wires, substantially as described.
93. In a machine for making wire fabric, 120 the combination with a rotary drum equipped with several opposite sets of twisters in pairs, each twister having an acting end face to engage the ends of the sections of a transverse stay wire and coil said ends around the 125 line wires, of means for leading line wires to the drum, and a stay carrier associated with said drum and operating to receive and de-

liver the transverse stay wire sections to the opposite rows of twisters, for the twisters to act and coil the ends of the transverse stay wire sections around the line wires, substantially as described.

94. In a machine for making wire fabric, the combination with a rotary drum equipped with several corresponding opposite sets of twisters in pairs, each twister having an acting end face to engage the ends of the sections of a transverse stay wire and coil said ends around the line wires, of means for leading line wires to the drum, and a stay carrier associated with said drum and operating to receive and deliver the transverse stay wire sections to the opposite rows of twisters, for the twisters to act and coil the ends of the transverse stay wire sections around the line wires, substantially as described.
- 10 95. In a machine for making wire fabric, the combination with a rotary drum, of two circumferentially opposite series of twisters mounted in pairs on the drum, each twister having an acting end face to engage and coil the ends of the sections of a transverse stay wire around the line wires, means for guiding a line wire to each opposite series of twisters, and means for guiding the sections of a transverse stay wire to corresponding pairs 15 of twisters in both opposite series of twisters, for the ends of the sections of the transverse stay wire to be coiled by the opposite pair of twisters upon both line wires, substantially as described.
- 20 96. In a machine for making wire fabric, the combination with a rotary weaving drum, of means for leading a plurality of line wires to the drum, and a revoluble stay carrier coöperating with the drum and adapted 25 to receive the sections of a transverse stay wire and deliver said sections to the drum, for the ends of the transverse stay wire sections to overlap adjacent line wires to be coiled around the line wires, substantially as described.
- 30 97. In a machine for making wire fabric, the combination with a frame, of a rotary weaving drum mounted therein, means for leading the line wire strands and the sections 35 of a transverse stay wire to the drum, for the ends of the transverse stay wire sections to be coiled around the line wires on the drum, a tension drum in advance of the weaving drum and around which the completed fabric passes from the weaving drum, a reel to receive the completed fabric from the tension drum, means for applying power to the tension drum, and gearing connecting said drum with the weaving drum and the reel respectively, for rotating the weaving drum, the tension drum and the reel continuously and in unison, substantially as described.
- 40 98. In a machine for making wire fabric, the combination with a rotary weaving drum, of a reel disposed to receive the com-

pleted fabric from the weaving drum, and a feed drum located between the reel and the weaving drum and engaging the completed fabric to effect the positive withdrawal thereof from the weaving drum, substantially as described.

99. In a machine for making wire fabric, the combination with wire connecting mechanism continuously movable in an endless orbit, said mechanism comprising opposite rows of twisters in pairs, each twister having an acting end face to engage the ends of the sections of a transverse stay wire and coil said ends around the line wires, of means for leading a plurality of line wires to said mechanism, and a stay carrier operative to receive the sections of a transverse stay wire and present said sections to the wire connecting mechanism and to the line wires, for the opposite twisters of the wire connecting mechanism to coil the ends of the transverse stay wire sections around the line wires, substantially as described.

100. In a machine for making wire fabric, the combination with means for continuously moving a plurality of line wires endwise, of twisting mechanism movable with the line wires, said mechanism comprising opposite rows of twisters arranged in pairs, each twister having an acting end face adapted to engage the ends of the sections of a transverse stay wire and coil said ends around the line wires, and means for moving the sections of the transverse stay wire sidewise to present the sections to the moving line wires and to the opposite row of twisters, for the twisters to act and coil the ends of the sections of the transverse stay wire around the line wires, substantially as described.

101. In a machine for making wire fabric, the combination with means for advancing a plurality of line wires, of continuously operating means for moving the sections of a transverse stay wire laterally to present said sections to the line wires with the ends of the sections overlapping the line wires, and twisting means, comprising opposite rows of twisters arranged in pairs, for the pairs of twisters to engage the overlapping ends of the sections of the stay wire and connect the same to the line wires by coiling the ends of the transverse stay wire sections around the line wires, substantially as described.

102. In a machine for making wire fabric, the combination with means for continuously advancing a plurality of line wires, of means for moving the sections of a transverse stay wire sidewise to present the sections of the transverse stay wire to the line wires during the advance movement of the latter for the ends of the sections of the transverse stay wire to overlap the line wires, and wire twisting means for connecting the line wires and the sections of the transverse stay wire, said wire twisting means comprising

opposite rows of twistors arranged in pairs, each twister having an acting end face to engage and coil the ends of the sections of the transverse stay wire around the line wires, substantially as described.

103. In a machine for making wire fabric, the combination with means for advancing a plurality of line wires, of mechanism operating during the movement of said wires to feed the sections of a transverse stay wire laterally to the line wires, with the ends of the sections of the transverse stay wire overlapping the line wires, and means operating to connect the sections of the transverse stay wire and the line wires, said mechanism including a pair of opposite twistors, each twister having an acting end face to engage the ends of the sections of the transverse stay wire and coil said ends around the line wires, substantially as described.

104. In a machine for making wire fabric, the combination with means for leading a plurality of wires longitudinally, of means for moving the sections of a transverse stay wire laterally to present said sections to the line wires with the ends of the sections overlapping the line wires, and twisting means for connecting the line wires and the sections of the transverse stay wire during their movement in unison, said twisting means comprising opposite rows of twistors arranged in pairs, each twister having an acting end face to engage the overlapping ends of the sections of the transverse stay wire and coil said ends around the line wires, substantially as described.

105. In a machine for making wire fabric, the combination with means for moving a line wire longitudinally, and means for moving the sections of a transverse stay wire sideways at the same time, and mechanism cooperating with the wire moving means to coil the ends of the stay wire sections around the line wire during their movement, said mechanism comprising an opposite pair of twistors, each twister having an acting end face to engage the ends of the sections of the transverse stay wire and coil said ends around the line wire, substantially as described.

106. In a machine for making wire fabric, means for continuously advancing a series of line wires, means located outside of said series of line wires, for feeding the sections of a transverse stay wire across said line wires, and means for effecting an interlocking connection of the sections of the transverse stay wire with certain or all of the line wires, said means comprising opposite rows of twistors arranged in pairs, each twister having an acting end face to engage the ends of the sections of the transverse stay wire and coil said ends around the line wires, substantially as described.

107. In combination, means for continuously advancing a plurality of line wires,

means for advancing the sections of a transverse stay wire across the line wires during the advance of the latter, wire connecting mechanism movable with the line wires in the direction of the feed thereof and operating during such movement to effect interlocking of the line wires and the sections of the transverse stay wire at their points of intersection, said mechanism comprising opposite rows of twistors arranged in pairs, each twister having an acting end face engaging the ends of the sections of the transverse stay wire for making the interlocking engagement at each point of intersection of the transverse stay wire sections and the line wires by coiling the ends of the stay wire sections to surround the line wires, substantially as described.

108. In a machine for making wire fabric, the combination with means for continuously advancing a series of line wires, means for intermittently advancing a plurality of wires to form the sections of a transverse stay wire, means for severing the plurality of wires into the sections of the transverse stay wire, means for moving the sections of the transverse stay wire with the line wires, and means for interweaving the sections of the transverse stay wire with the line wires during the advance of the latter, said means comprising opposite rows of twistors arranged in pairs, each twister having an acting end face to engage the ends of the sections of the transverse stay wire and coil said ends around the line wires, substantially as described.

109. In a machine for making wire fabric, the combination with means for continuously advancing a plurality of line wires, of means mounted to travel with the line wires, said means comprising opposite rows of twistors arranged in pairs, each twister having an acting end face to engage the ends of the sections of a transverse stay wire and interweave the transverse stay wire sections with the several line wires by coiling the ends of the transverse stay wire sections around the line wires, and means for severing a plurality of wires to form the sections of the transverse stay wire, substantially as described.

110. In a machine for making wire fabric, the combination with means for advancing a series of line wires, of means for feeding the sections of a transverse stay wire across the series of line wires by a continuous movement, for the ends of the sections of the transverse stay wire to overlap the line wires, and means for thereafter coiling the ends of the stay wire sections upon the line wires during the advance of the latter, said means comprising opposite rows of twistors arranged in pairs, each twister having an acting end face to engage the ends of the sections of the transverse stay wire and coil said sections around the line wires, substantially as described.

rows of twister heads mounted on said rails, rows of stay wire section grippers carried on said rails in intermediate relation to the twister heads, means for electro-magnetically operating the grippers, and means for feeding a series of stay wire sections to the grippers, said carrying rails having a circular travel in unison with the strand wires during the twisting and coiling of the stay wire sections thereon. 5

123. In a wire fence machine, the combination of a series of carrying rails, rows of twister heads mounted thereon, and a traveling stay wire section carrier adapted to deliver a series of stay wire sections to the twister heads with the ends of each stay wire section overlapping adjacent strand wires, the said rails having an endless travel in unison with the strand wires during the twisting and coiling of the stay wire sections thereon. 10

124. In a wire fence machine, the combination of a series of carrying rails, opposite rows of twister heads mounted thereon, and a traveling stay wire section carrier adapted to deliver a series of stay wires to the twister heads with the ends of each stay wire section overlapping adjacent strand wires, the said rails having an endless travel in unison with the strand wires during the twisting and coiling of the stay wire sections thereon. 15

125. In a wire fence machine, the combination of a series of carrying rails, rows of twister heads mounted on said rails, rows of stay wire section grippers carried on said rails in intermediate relation to the twister heads, and a traveling stay wire section carrier adapted to deliver a series of stay wire sections to the grippers with the ends of each stay wire section overlapping adjacent strand wires, the said rails having an endless travel in unison with the strand wires during the twisting and coiling of the stay wires thereon. 20

126. In a wire fence machine, the combination of a series of carrying rails, opposite rows of twister heads mounted on said rails, rows of stay wire section grippers carried on said rails in intermediate relation to the twister heads, and a traveling stay wire section carrier adapted to deliver a series of stay wire sections to the grippers with the ends of each stay wire section overlapping adjacent strand wires, the said rails having an endless travel in unison with the strand wires during the twisting and coiling of the stay wire sections thereon. 25

127. In a wire fence machine, the combination of a series of carrying rails, rows of twister heads mounted on said rails, rows of stay wire section grippers carried on said rails in intermediate relation to the twister heads, means for electro-magnetically operating said grippers, and a traveling stay wire section carrier adapted to deliver a series of stay

wire sections to the grippers with the ends of each stay wire section overlapping adjacent strand wires, the said rails having an endless travel in unison with the strand wires during the twisting and coiling of the stay wire sections thereon. 30

128. In a wire fence machine, the combination of a series of carrying rails, rows of twister heads mounted thereon, and a traveling electro-magnetic carrier adapted to deliver a series of stay wire sections to the twister heads with the ends of each stay wire section overlapping adjacent strand wires, said rails having an endless travel in unison with the strand wires during the twisting and coiling of the stay wire sections thereon. 35

129. In a wire fence machine, the combination of a series of carrying rails, opposite rows of twister heads mounted thereon, and a traveling electro-magnetic carrier adapted to deliver a series of stay wire sections to the twister heads with the ends of each stay wire section overlapping adjacent strand wires, said rails having an endless travel in unison with the strand wires during the twisting and coiling of the stay wire sections thereon. 40

130. In a wire fence machine, the combination of a series of carrying rails, rows of twister heads mounted on said rails, rows of stay wire section grippers carried on said rails in intermediate relation to the twister heads, and a traveling electro-magnetic carrier adapted to deliver a series of stay wire sections to the grippers with the ends of each stay wire section overlapping adjacent strand wires, the said rails having an endless travel in unison with the strand wires during the twisting and coiling of the stay wire sections thereon. 45

131. In a wire fence machine, the combination of a series of carrying rails, opposite rows of twister heads mounted on said rails, rows of stay wire section grippers carried on said rails in intermediate relation to the twister heads, and a traveling electro-magnetic carrier adapted to deliver a series of stay wire sections to the grippers with the ends of each stay wire section overlapping adjacent strand wires, the said rails having an endless travel in unison with the strand wires during the twisting and coiling of the stay wire sections thereon. 50

132. In a wire fence machine, the combination of a series of carrying rails, rows of twister heads mounted on said rails, rows of stay wire section grippers carried on said rails in intermediate relation to the twister heads, means for electro-magnetically operating said grippers, and a traveling electro-magnetic carrier adapted to deliver a series of stay wire sections to the grippers with the ends of each stay wire section overlapping adjacent strand wires, the said rails having an endless travel in unison with the strand wires during the twisting and coiling of the stay wire sections thereon. 55

wires during the twisting and coiling of the stay wire sections thereon.

133. In a wire fence machine, the combination of a series of carrying rails, rows of 5 twister heads mounted on said rails, a row of stay wire cutting mechanisms, and an electro-magnetic carrier adapted to take the stay wire sections from the cutting mechanisms and deliver the same to the twister heads 10 with the ends of each stay wire section overlapping adjacent strand wires, the said rails having an endless travel in unison with the strand wires during the twisting and coiling of the stay wire sections thereon.

134. In a wire fence machine, the combination of a series of carrying rails, opposite rows of twister heads mounted thereon, a 15 row of stay wire cutting mechanisms, and an electro-magnetic carrier adapted to take the 20 stay wire sections from the cutting mechanisms and deliver the same to the twister heads with the ends of each stay wire section overlapping adjacent strand wires, the said rails having an endless travel in unison with 25 the strand wires during the twisting and coiling of the stay wire sections thereon.

135. In a wire fence machine, the combination of a series of carrying rails, rows of 30 twister heads mounted on said rails, rows of stay wire section grippers carried on said rails in intermediate relation to the twister heads, a row of stay wire cutting mechanisms, and an electro-magnetic carrier adapted to take the stay wire sections from the cutting mechanisms and deliver the same to the 35 grippers with the ends of each stay wire section overlapping adjacent strand wires, the said rails having an endless travel in unison with the strand wires during the twisting and 40 coiling of the stay wire sections thereon.

136. In a wire fence machine, the combination of a series of carrying rails, opposite rows of twister heads mounted thereon, rows of stay wire section grippers carried on said 45 rails in intermediate relation to the twister heads, a row of stay wire cutting mechanisms, and an electro-magnetic carrier adapted to take the stay wire sections from the cutting mechanisms and deliver the same to the 50 grippers with the ends of each stay wire section overlapping adjacent strand wires, the said rails having an endless travel in unison with the strand wires during the twisting and coiling 55 of the stay wire sections thereon.

137. In a wire fence machine, the combination of a series of carrying rails, rows of twister heads mounted thereon, a row of stay wire section grippers carried on said rails in intermediate relation to the twister heads, 60 means for electro-magnetically operating the grippers, a row of stay wire cutting mechanisms, and an electro-magnetic carrier adapted to take the stay wire sections from the cutting mechanisms and deliver the same to the 65 grippers with the ends of each stay wire sec-

tion overlapping adjacent strand wires, the said rails having an endless travel in unison with the strand wires during the twisting and coiling of the stay wire sections thereon.

138. In a wire fence machine, the combination of a rotary weaving head, opposite rows of twister heads mounted thereon, and means for feeding a series of stay wire sections to the twister heads with the ends of each stay wire section overlapping adjacent 70 strand wires, the weaving head having a circular travel in unison with the strand wires during the twisting and coiling of the stay wire sections thereon.

139. In a wire fence machine, the combination of a rotary weaving head, rows of 80 twister heads mounted thereon, rows of stay wire section grippers carried on said weaving head in intermediate relation to the twister heads, and means for feeding a series of stay 85 wire sections to the grippers with the ends of each stay wire section overlapping adjacent strand wires, said weaving head having a circular travel in unison with the strand wires during the twisting and coiling of the stay 90 wire sections thereon.

140. In a wire fence machine, the combination of a rotary weaving head, opposite rows of twister heads mounted thereon, rows of stay wire section grippers carried on said 95 weaving head in intermediate relation to the twister heads, and means for feeding a series of stay wire sections to the grippers with the ends of each stay wire section overlapping adjacent strand wires, said weaving head 100 having a circular travel in unison with the strand wires during the twisting and coiling of the stay wire sections thereon.

141. In a wire fence machine, the combination of a rotary weaving head, rows of 105 twister heads mounted thereon, rows of stay wire section grippers carried on said weaving head in intermediate relation to the twister heads, means for electro-magnetically operating the grippers, and means for feeding a 110 series of stay wire sections to the grippers with the end of each stay wire section overlapping adjacent strand wires, said weaving head having a circular travel in unison with the strand wires during the twisting and coiling 115 of the stay wire sections thereon.

142. In a wire fence machine, the combination of a rotary weaving head, opposite rows of twister heads mounted thereon, rows of stay wire section grippers carried on said 120 weaving head in intermediate relation to the twister heads, means for electro-magnetically operating the grippers, and means for feeding a series of stay wire sections to the grippers with the ends of each stay wire section overlapping adjacent strand wires, said weaving head having a circular travel in unison with the strand wires during the twisting and coiling 125 of the stay wire sections thereon.

143. In a wire fence machine, the combi- 130

- nation of a rotary weaving head, rows of 5
twister heads mounted thereon, and a traveling stay wire section carrier adapted to de-
liver a series of stay wire sections to the
twister heads with the ends of each stay wire
section overlapping adjacent strand wires,
said weaving head having a circular travel in
unison with the strand wires during the
twisting and coiling of the stay wire sections
thereon.
144. In a wire fence machine, the combination of a rotary weaving head, opposite rows of twister heads mounted thereon, and a traveling stay wire section carrier adapted 15 to deliver a series of stay wire sections to the twister heads with the ends of each stay wire section overlapping adjacent strand wires, said weaving head having a circular travel in unison with the strand wires during the 20 twisting and coiling of the stay wire sections thereon.
145. In a wire fence machine, the combination of a rotary weaving head, rows of 25 twister heads mounted thereon, rows of stay wire section grippers carried on said weaving head in intermediate relation to the twister heads, and a traveling stay wire section carrier adapted to deliver a series of stay wire sections to the grippers with the 30 ends of each stay wire section overlapping adjacent strand wires, said weaving head having a circular travel in unison with the strand wires during the twisting and coiling of the stay wire sections thereon.
146. In a wire fence machine, the combination of a rotary weaving head, opposite rows of twister heads mounted thereon, rows of stay wire section grippers carried on said 35 weaving head in intermediate relation to the twister heads, and a traveling stay wire section carrier adapted to deliver a series of stay wire sections to the grippers with the 40 ends of each stay wire section overlapping adjacent strand wires, said weaving head having a circular travel in unison with the strand wires during the twisting and coiling 45 of the stay wire sections thereon.
147. In a wire fence machine, the combination of a rotary weaving head, rows of 50 twister heads mounted thereon, rows of stay wire section grippers carried on said weaving head in intermediate relation to the twister heads, means for electro-magnetically operating the grippers, and a traveling stay wire 55 section carrier adapted to deliver a series of stay wire sections to the grippers with the ends of each stay wire section overlapping adjacent strand wires, said weaving head having a circular travel in unison with the 60 strand wires during the twisting and coiling of the stay wire sections thereon.
148. In a wire fence machine, the combination of a rotary weaving head, rows of 65 twister heads mounted thereon, and a traveling electro-magnetic carrier adapted to de-
- liver a series of stay wire sections to the twister heads with the ends of each stay wire section overlapping adjacent strand wires, said weaving head having a circular travel in unison with the strand wires during the 70 twisting and coiling of the stay wire sections thereon.
149. In a wire fence machine, the combination of a rotary weaving head, opposite rows of twister heads mounted thereon, and a traveling electro-magnetic carrier adapted 75 to deliver a series of stay wire sections to the twister heads with the ends of each stay wire section overlapping adjacent strand wires, said weaving head having a circular travel 80 in unison with the strand wires during the twisting and coiling of the stay wire sections thereon.
150. In a wire fence machine, the combination of a rotary weaving head, rows of 85 twister heads mounted thereon, rows of stay wire section grippers carried on said weaving head in intermediate relation to the twister heads, and a traveling electro-magnetic carrier adapted to deliver a series of stay wire 90 sections to the grippers with the ends of each stay wire section overlapping adjacent strand wires, said weaving head having a circular travel in unison with the strand wires during the twisting and coiling 95 of the stay wire sections thereon.
151. In a wire fence machine, the combination of a rotary weaving head, opposite rows of twister heads mounted thereon, rows of stay wire section grippers carried on said 100 weaving head in intermediate relation to the twister heads, and a traveling electro-magnetic carrier adapted to deliver a series of stay wire sections to the grippers with the 105 ends of each stay wire section overlapping adjacent strand wires, said weaving head having a circular travel in unison with the strand wires during the twisting and coiling 110 of the stay wire sections thereon.
152. In a wire fence machine, the combination of a rotary weaving head, rows of 115 twister heads mounted thereon, rows of stay wire section grippers carried on said weaving head in intermediate relation to the twister heads, means for electro-magnetically operating the grippers, and a traveling electro-magnetic carrier adapted to deliver a series 120 of stay wire sections to the grippers with the ends of each stay wire section overlapping adjacent strand wires, said weaving head having a circular travel in unison with the strand wires during the twisting and coiling 125 of the stay wire sections thereon.
153. In a wire fence machine, the combination of a rotary weaving head, rows of 125 twister heads mounted thereon, a row of stay wire cutting mechanisms, and an electro-magnetic carrier adapted to take the stay wire sections from the cutting mechanisms 130 and deliver the same to the twister heads.

with the ends of each stay wire section overlapping adjacent strand wires, said weaving head having a circular travel in unison with the strand wires during the twisting and coiling of the stay wire sections thereon.

154. In a wire fence machine, the combination of a rotary weaving head, opposite rows of twister heads mounted thereon, a row of stay wire cutting mechanisms, and an electro-magnetic carrier adapted to take the stay wire sections from the cutting mechanisms and deliver the same to the twister heads with the ends of each stay wire section overlapping strand wires, said weaving head having a circular travel in unison with the strand wires during the twisting and coiling of the stay wire sections thereon.

155. In a wire fence machine, the combination of a rotary weaving head, rows of twister heads mounted thereon, rows of stay wire section grippers carried on said weaving head in intermediate relation to the twister heads, a row of stay wire cutting mechanisms, and an electro-magnetic carrier adapted to take the stay wire sections from the cutting mechanisms and deliver the same to the grippers with the ends of each stay wire section overlapping adjacent strand wires, said weaving head having a circular travel in unison with the strand wires during the twisting and coiling of the stay wire sections thereon.

156. In a wire fence machine, the combination of a rotary weaving head, opposite rows of twister heads mounted thereon, rows of stay wire section grippers carried on said weaving head in intermediate relation to the twister heads, a row of stay wire cutting mechanisms, and an electro-magnetic carrier adapted to take the stay wire sections from the cutting mechanisms and deliver the same to the grippers with the ends of each stay wire section overlapping adjacent strand wires, said weaving head having a circular travel in unison with the strand wires during the twisting and coiling of the stay wire sections thereon.

157. In a wire fence machine, the combination of a rotary weaving head, rows of twister heads mounted thereon, rows of stay wire section grippers carried on said weaving head in intermediate relation to the twister heads, means for electro-magnetically operating the grippers, a row of stay wire cutting mechanisms, and an electro-magnetic carrier adapted to take the stay wire sections from the cutting mechanisms and deliver the same to the grippers with the ends of each stay wire section overlapping adjacent strand wires, said weaving head having a circular travel in unison with the strand wires during the twisting and coiling of the stay wire sections thereon.

158. In a wire fence machine, a stay wire feeding mechanism comprising a driven feed

wheel, a driven tension roll having adjacent peripheral relation to the feed wheel, means for retarding the travel of the stay forming wire towards the feed wheel, a stationary breast arranged tangentially to the feed wheel, and a holding lever operating in unison with the tension roll to intermittently clamp the end of the stay wire upon such breast.

159. In a wire fence machine, a stay wire feeding mechanism comprising a driven feed wheel, a positively driven tension roll having a mutilated periphery, means for forming a bend or bight in the stay forming wire upon or around said feed wheel, a stationary breast arranged tangentially to the feed wheel, and a holding lever operating in unison with the tension roll to intermittently clamp the end of the stay wire upon such breast.

160. In a wire fence machine, a stay wire feeding mechanism comprising a driven feed wheel, a tension roll intergeared therewith and having a portion of its periphery removed, means for forming a bend or bight in the stay forming wire upon or around said feed wheel, a stationary breast arranged tangentially to the feed wheel, and a holding lever operating in unison with the tension roll to intermittently clamp the end of the stay wire upon such breast.

161. In a wire fence machine, a stay wire feeding mechanism comprising a driven feed wheel having a channeled periphery, a positively driven tension roll having a mutilated periphery, means for forming a bend or bight in the stay forming wire upon or around said feed wheel, a stationary breast arranged tangentially to the feed wheel, and a holding lever operating in unison with the tension roll to intermittently clamp the end of the stay wire upon such breast.

162. In a wire fence machine, a stay wire feeding mechanism comprising a driven feed wheel having a channeled periphery, a tension roll intergeared therewith and having a portion of its periphery removed, means for forming a bend or bight in the stay wire upon or around said feed wheel, a stationary breast arranged tangentially to said feed wheel, and a holding lever operating in unison with the tension roll to intermittently clamp the end of the stay wire upon such breast.

163. In a wire fence machine, a stay wire feeding mechanism comprising a driven feed wheel, a positively driven tension roll having a mutilated periphery, means for forming a bend or bight in the stay forming wire upon or around said feed wheel, a stationary breast arranged tangentially to the feed wheel, and a holding lever having a resilient toe and operating in unison with the tension roll to intermittently clamp the end of the stay wire upon such breast.

164. In a wire fence machine, a stay wire feeding mechanism comprising a driven feed

- wheel, a tension roll intergeared therewith and having a portion of its periphery removed, means for forming a bend or bight in the stay forming wire upon or around said feed wheel, forming wire upon or around said feed wheel, and a holding lever having a resilient toe and operating in unison with the tension roll to intermittently clamp the end of the stay wire upon such breast.
- 5 165. In a wire fence machine, a stay wire feeding mechanism comprising a driven feed wheel having a channeled periphery, a positively driven tension roll having a mutilated periphery, means for forming a bend or bight in the stay forming wire upon or around said feed wheel, a stationary breast arranged tangentially to the feed wheel, and a holding lever having a resilient toe and operating in unison with the tension roll to intermittently clamp the end of the stay wire upon such breast.
- 10 166. In a wire fence machine, a stay wire feeding mechanism comprising a driven feed wheel having a channeled periphery, a tension roll intergeared therewith and having a portion of its periphery removed, means for forming a bend or bight in the stay wire upon or around said feed wheel, a stationary breast arranged tangentially to the feed wheel, and a holding lever having a resilient toe and operating in unison with the tension roll to intermittently clamp the end of the stay wire upon said breast.
- 15 167. In a wire fence machine, a stay wire feeding mechanism comprising a driven feed wheel, a positively driven tension roll having a mutilated periphery, a wire straightening mechanism affording means for retarding the travel of the stay forming wire towards the feed wheel, a stationary breast arranged tangentially to the feed wheel, and a holding lever operating in unison with the tension roll to intermittently clamp the end of the stay wire upon such breast.
- 20 168. In a wire fence machine, a stay wire feeding mechanism comprising a driven feed wheel, a tension roll intergeared therewith and having a portion of its periphery removed, a wire straightening mechanism affording means for retarding the travel of the stay forming wire towards the feed wheel, a stationary breast arranged tangentially to the feed wheel, and a holding lever operating in unison with the tension roll to intermittently clamp the end of the stay wire upon such breast.
- 25 169. In a wire fence machine, a stay wire feeding mechanism comprising a feed wheel having a channeled periphery, a positively driven tension roll having a mutilated periphery, a wire straightening mechanism affording means for retarding travel of the stay forming wire towards the feed wheel, a stationary breast arranged tangentially to the feed wheel, and a holding lever operating in unison with the tension roll to intermittently clamp the end of the stay wire upon such breast.
- 30 170. In a wire fence machine, a stay wire feeding mechanism comprising a driven feed wheel having a channeled periphery, a tension roll intergeared therewith and having a portion of its periphery removed, a wire straightening mechanism affording means for retarding the travel of the stay forming wire towards the feed wheel, a stationary breast arranged tangentially to said feed wheel, and a holding lever operating in unison with the tension roll to intermittently clamp the end of the stay wire upon such breast.
- 35 171. In a wire fence machine, a stay wire cutting mechanism comprising a series of stationary posts, a series of stationary shear blocks attached thereto in an adjustable manner, a series of movable cutter heads carried by said posts, an interchangeable series of sleeves arranged on said posts beneath the movable cutter heads, and means for operating the movable cutter heads.
- 40 172. In a wire fence machine, a stay wire cutting mechanism comprising a series of stationary posts, a series of stationary shear blocks attached thereto in an adjustable manner, a series of movable cutter heads carried by said posts, an interchangeable series of sleeves arranged on said posts beneath the movable cutter heads, and means for operating the movable cutter heads, the same comprising individual arms on said cutter heads, a reciprocating bar, and a series of blocks carried by said bar and formed with elongated channels for engagement with the ends of said arms.
- 45 173. In a wire fence machine, a stay wire section carrier comprising a revoluble supporting frame, a circular series of rails carried on said frame, each rail having a row of radial journal orifices, a series of heads journaled in said orifices, a series of rack-bars, each rack-bar common to a row of said heads and intergeared therewith, a cam for imparting reciprocation to said rack-bars, a series of electro-magnetic stay wire section holders or grippers carried on the outer ends of said heads, and means for intermittently energizing the same.
- 50 174. In a wire fence machine, a stay wire section carrier comprising a revoluble supporting frame, a circular series of rails carried on said frame, each rail having a row of radial journal orifices, a series of heads journaled in said orifices, a series of rack-bars, each rack-bar common to a row of said heads and intergeared therewith, a cam for imparting reciprocation to said rack-bars, a series of electro-magnetic stay wire section holders or grippers secured in an individually adjustable manner to said heads, and means for intermittently energizing said holders or grippers.
- 55 175. In a wire fence machine, the combi-

- nation of a series of carrying rails, rows of 1
 twister heads mounted on said rails, means 5
 for imparting axial reciprocation to said
 heads, and means for feeding a series of stay
 5 wire sections to the twister heads in trans-
 verse relation to the strand wires, the rails
 and twister heads having a travel in unison
 with the strand wires during the twisting and
 coiling of the stay wire sections thereon. 10
176. In a wire fence machine, the combi- 10
 nation of a series of carrying rails, rows of
 twister heads mounted on said rails, means
 for imparting axial reciprocation to said
 heads, and means for feeding a series of stay
 15 wire sections to the twister heads in trans-
 verse relation to the strand wires, the rails
 and twister heads having an endless travel in
 unison with the strand wires during the
 twisting and coiling of the stay wire sections 20
177. In a wire fence machine, the combi- 20
 nation of a series of carrying rails, rows of
 twister heads mounted on said rails, means
 for imparting axial reciprocation to said
 heads, and means for feeding a series of stay
 25 wire sections to the twister heads in trans-
 verse relation to the strand wires, the rails
 and twister heads having a circular travel in
 unison with the strand wires during the
 twisting and coiling of the stay wire sections 30
178. In a wire fence machine, the combi- 30
 nation of a series of carrying rails, rows of
 twister heads mounted on said rails, means
 for imparting intermittent axial reciproca- 35
 tion to said heads, rows of stay wire section
 grippers carried on said rails in intermediate
 relation to the twister heads, and means for
 feeding a series of stay wire sections to the
 40 grippers in transverse relation to the strand
 wires, said carrying rails having a travel in
 unison with the strand wires during the
 twisting and coiling of the stay wire sections
 thereon. 45
179. In a wire fence machine, the combi- 45
 nation of a series of carrying rails, rows of
 twister heads mounted on said rails, means
 for imparting intermittent axial reciproca- 50
 tion to said heads, rows of stay wire section
 grippers carried on said rails in intermediate
 relation to the twister heads, and means for
 feeding a series of stay wire sections to the
 55 grippers in transverse relation to the strand
 wires, said carrying rails having an endless
 travel in unison with the strand wires during
 the twisting and coiling of the stay wire sec-
 tions thereon. 60
180. In a wire fence machine, the combi- 60
 nation of a series of carrying rails, rows of twister
 heads mounted on said rails, means for im-
 parting intermittent axial reciprocation to
 said heads, rows of stay wire section grippers
 carried on said rails in intermediate relation 65
 to the twister heads, and means for feeding a
 series of stay wire sections to the grippers in
 transverse relation to the strand wires, said carry- 70
 ing rails having a circular travel in unison
 with the strand wires during the twisting and
 coiling of the stay wire sections thereon. 75
181. In a wire fence machine, the combi- 75
 nation of a series of carrying rails, opposite
 rows of twister heads mounted on said rails,
 means for imparting intermittent axial re- 80
 ciprocalation to opposite pairs of said heads,
 and means for feeding a series of stay wire
 sections to the twister heads in transverse
 relation to the strand wires, the rails and
 twister heads having a travel in unison with 85
 the strand wires during the twisting and coil-
 ing of the stay wire sections thereon. 90
182. In a wire fence machine, the combi- 90
 nation of a series of carrying rails, opposite
 rows of twister heads mounted on said rails,
 means for imparting intermittent axial re- 95
 ciprocalation to opposite pairs of said heads,
 and means for feeding a series of stay wire
 sections to the twister heads in transverse
 relation to the strand wires, the rails and
 twister heads having an endless travel in 100
 unison with the strand wires during the
 twisting and coiling of the stay wire sections
 thereon. 105
183. In a wire fence machine, the combi- 105
 nation of a series of carrying rails, opposite
 rows of twister heads mounted on said rails,
 means for imparting intermittent axial re- 110
 ciprocalation to opposite pairs of said heads,
 and means for feeding a series of stay wire
 sections to the twister heads in transverse
 relation to the strand wires, the rails and
 twister heads having a circular travel in 115
 unison with the strand wires during the
 twisting and coiling of the stay wire sections
 thereon. 120
184. In a wire fence machine, the combi- 120
 nation of a series of carrying rails, opposite
 rows of twister heads mounted on said rails,
 means for imparting intermittent axial re- 125
 ciprocalation to opposite pairs of said heads,
 rows of stay wire section grippers carried on
 said rails in intermediate relation to the
 twister heads, and means for feeding a series
 of stay wire sections to the grippers in trans- 130
 verse relation to the strand wires, said carry-
 ing rails having an endless travel in unison
 with the strand wires during the twisting and
 coiling of the stay wire sections thereon. 135
185. In a wire fence machine, the combi- 135
 nation of a series of carrying rails, opposite
 rows of twister heads mounted on said rails,
 means for imparting intermittent axial re- 140
 ciprocalation to opposite pairs of said heads,
 rows of stay wire section grippers carried on
 said rails in intermediate relation to the
 twister heads, and means for feeding a series
 of stay wire sections to the grippers in trans- 145
 verse relation to the strand wires, said carry-

ing rails having a circular travel in unison with the strand wires during the twisting and coiling of the stay wire sections thereon.

186. In a wire fence machine, a weaving mechanism comprising a revoluble frame, a circular series of rails mounted in guides on said frame, means for imparting individual movement to said rails comprising a stationary cam and a series of intermediate mechanisms between the cam and the rails, a series of twister heads journaled in said rails, means for imparting varied rotation to said twister heads, comprising a series of rack-bars and a stationary cam common to said rack-bars, means for feeding a series of stay wire sections to the twister heads, and means for imparting rotation to the rail carrying frame.

187. In a wire fence machine, a weaving mechanism comprising a revoluble frame, a circular series of rails arranged in opposite pairs and mounted in guides on said frame, means for imparting individual adjustment to said rails comprising a stationary cam and a series of intermediate mechanisms between said cam and the rails, opposite rows of twister heads journaled in said rails, means for imparting varied rotation to said twister heads comprising a series of rack-bars and a stationary cam common to said rack-bars, means for feeding a series of stay wire sections to the twister heads, and means for imparting rotation to the rail carrying frame.

188. In a wire fence machine, a weaving mechanism comprising a revoluble frame, a circular series of rails mounted in guides on said frame, means for imparting individual movement to said rails comprising a stationary cam and a series of intermediate mechanisms between the cam and the rails, means for effecting a turning adjustment of said cam comprising a stationary segmental shoe to which said cam is peripherally attached in an adjustable manner, a series of twister heads journaled in said rails, means for imparting varied rotation to said twister heads comprising a series of rack-bars and a stationary cam common to said rack-bars, means for feeding a series of stay wire sections to the twister heads, and means for imparting rotation to the rail carrying frame.

189. In a wire fence machine, a strand crimping mechanism comprising a pair of carrying shafts, series of rotary crimping heads carried thereon in longitudinal spaced relation, a series of shoes having intermediate bearings on said shafts, a pair of girders carrying said shoes, and tie bolts connecting the girders together.

190. In a wire fence machine, a mechanism for forming an interlocked twist of adjacent stay wire section ends upon a strand wire, comprising a pair of opposite twister heads each having a single coiling pin, means

for holding said stay wire sections with their ends overlapping the strand wire, means for imparting a partial forward rotation to the twister heads and a simultaneous movement towards each other, means for effecting a subsequent moving apart of the twister heads and a further partial forward rotation of the same, means for then moving the twister heads towards each other, means for then imparting one or more reverse rotations to the twister heads, and means for then returning the twister heads to their initial position.

191. In a wire fence machine, a mechanism for forming an interlocked twist of adjacent stay wire section ends upon a strand wire, comprising a pair of opposite twister heads each having a single coiling pin, means for holding said stay wire sections with their ends overlapping the strand wire, means for imparting a partial forward rotation to the twister heads and a simultaneous movement towards each other, means for then effecting a slight reverse rotation, a moving apart, and a further partial forward rotation of the twister heads, means for then moving the twister heads toward each other, means for then imparting one or more reverse rotations to the twister heads, and means for then returning the twister heads to their initial position.

192. In a wire fence machine, the combination of a rotary weaving head over which the strand wires lead, mechanism for continuously feeding forward a plurality of strand wires, mechanism for intermittently feeding forward a plurality of stay wires, and mechanism for severing the advanced portion of each stay wire to form a section of a transverse stay crossing the plurality of strand wires, substantially as described.

193. In a wire fence machine, the combination of a rotary weaving head over which the strand wires lead, mechanism for continuously feeding forward a plurality of strand wires, mechanism for intermittently feeding forward a plurality of stay wires, mechanism for severing the advanced portion of each stay wire to form a section of a transverse stay crossing the plurality of strand wires, and means for delivering the severed stay sections into position for coiling their ends around the strand wires, substantially as described.

194. In a wire fence machine, the combination of a rotary weaving head over which the strand wires lead, mechanism for continuously feeding forward a plurality of strand wires, mechanism for intermittently feeding forward a plurality of stay wires, mechanism for severing the advanced portion of each stay wire to form a section of a transverse stay crossing the plurality of strand wires, means for delivering the severed stay sections into position for coiling their ends around the

strand wires, and a series of twister heads mounted on the rotary weaving head, and over the acting ends of which the severed sections of the stay are delivered, substantially as described.

195. In a wire fence machine, the combination of a rotary weaving head over which the strand wires lead, mechanism for continuously feeding forward a plurality of strand

10 wires, mechanism for intermittently feeding forward a plurality of stay wires, mechanism for severing the advanced portion of each stay wire to form a section of a transverse stay crossing the plurality of strand wires,

15 means for delivering the severed stay sections into position for coiling their ends around the strand wires, a series of twister heads mounted on the rotary weaving head and over the acting ends of which the severed sections of

20 the stay are delivered, and means for revolving the series of twister heads simultaneously for coiling the ends of the severed sections of the stay around the strand wires, substantially as described.

25 196. In a wire fence machine, the combination of a rotary weaving head, means for continuously feeding forward a plurality of strand wires over the rotary weaving head, mechanism for downwardly and intermittently feeding a plurality of stay wires, mechanism for severing the advanced portion of each stay

wire into a section of a transverse stay for the ends of each stay wire section to overlap adjacent strand wires, and mechanism for turning each vertical severed stay section into a horizontal position and delivering the section across the strand wires, substantially as described.

197. In a wire fence machine, the combination of a rotary weaving head, means for continuously feeding forward a plurality of strand wires over the rotary weaving head, mechanism for downwardly and intermittently feeding a plurality of stay wires, mechanism for severing the advanced portion of each stay wire into a section of a transverse stay for the ends of each stay wire section to overlap adjacent strand wires, mechanism for turning each vertical severed stay section into a horizontal position and delivering the section across the strand wires, and rows of twister heads mounted on the rotary weaving head for twisting and coiling the ends of the severed stay sections around adjacent strand wires, substantially as described.

Signed at Rock Falls, Illinois, this 27th day of November 1905. 55

WARD W. LINCOLN.
